UNITED STATES PATENT OFFICE.

WILLIAM E. BRAND, OF BOSTON, MASSACHUSETTS, ASSIGNOR TO MONOMAN TYPESETTER COMPANY, OF NEW YORK, N. Y., A CORPORATION OF NEW YORK.

TYPE CASTING AND COMPOSING MACHINE.

No. 862,800.

Specification of Letters Patent.

Patented Aug. 6, 1907.

Application filed May 31, 1907. Serial No. 376,534.

To all whom it may concern:

Be it known that I, WILLIAM E. BRAND, a citizen of the United States, residing at Boston, in the county of Suffolk and State of Massachusetts, have invented certain new and useful Improvements in Type Casting and Composing Machines; and I do hereby declare the following to be a full, clear, and exact description of the same.

My invention relates to type-casting and composing machines—more particularly to that class of composing machines in which the line is preliminarily represented on a controller, which afterwards comes into effect to control the operation of the casting mechanism. Many of the improvements are, however, equally well adapted for use in connection with other forms of typographic machines.

The general method heretofore employed has been to prepare the controller—usually a strip of paper—on a separate key-board or perforating machine, and then take the roll of paper to the casting machine. This requires two men or two operations. I have provided a mechanical controller in the form of an endless belt or chain, having movable actuating pins, which belt is sufficiently long to enable the operator to get several lines ahead of the machine; and I have combined the key-board and casting mechanism into one machine, thereby not only saving the cost of the paper, but saving one operation and making a one-man machine of it.

Another improvement consists in a place-finder. Heretofore, an operator at a key-board that did not have a typewriter or printing attachment has had no means of telling where he left off, unless he remembered his place or marked his copy. I have provided an indicator, without a printing attachment, which enables the operator to read the controller, to find and keep his place—thereby relieving him of considerable strain and rendering errors much less liable.

Another improvement consists in providing low space quads. Heretofore, on machines of this class, the spaces and quads have been full shoulder-high. This is a great inconvenience, especially where the printing is done directly from the type.

Another improvement consists in providing an alarm to inform the operator when a matrix gets stopped up. In machines of this class, the matrices will sometimes become clogged, and a whole galley of type will be cast with one letter dropped out, a blank being cast in its stead. This makes a lot of work for the proof-reader and the man who corrects the matter, which my improvement renders entirely unnecessary.

Another improvement consists in a simplified counting device and justifier which enables me, in using a quotient and remainder justifier, to reduce the size of

the unit to one-half that formerly employed, without increasing the number of combinations; thus permitting practically the duplication of any face of type, instead of being confined to what is known as "self-spacing type", where all the type are cast on one of five or six fixed sizes, varying from each other by substantial units of difference. Furthermore, I have provided an improved alining device for the matrices, designed especially to give absolute alinement and one which ordinary wear will not affect.

Another improvement consists in the form of matrix- or die-case which permits the type being put in the line of assembly on moving them but a short distance from the place where they are cast. I have also designed a novel movement to control the positions of the matrix case.

A still further improvement consists in providing a set-size index for the matrix-case. Heretofore the running widths or sizes of the type have been indicated on the controller, or the same sizes have been grouped together in the matrix-case. My plan enables me to utilize the advantages of both the old methods.

Other improvements will be described in the specifications and pointed out in the claims.

In the following description reference is made to the accompanying drawings in which:

Figure 1 is a plan. Fig. 2 is a right elevation. Fig. 3 is a left elevation. Fig. 4 is a front elevation. Fig. 5 is a rear elevation. Fig. 6 is a right sectional elevation on line A—A. Fig. 7 is a detail of the matrix placing devices—the section being taken about on line indicated by arrow B of Fig. 6. Figs. 8 and 9 are detached parts of the same mechanism and Fig. 9^a represents an alternative construction. Fig. 10 is a detail showing connection of key lever. Fig. 11 is a right sectional elevation through the key-board about on line C—C. Fig. 12 is a section through the cover slide and adjacent typeway about on line D—D of Fig. 26. Fig. 13 is a front elevation of the counting devices, the section being taken about on line E—E of Fig. 11. Fig. 14 is a plan detail showing the star wheel to feed the controller and showing four bars of the controller raised to horizontal position. Fig. 15 is a detail showing a section through the controller which might be taken opposite any of the sprocket wheels. Fig. 16 is a detail section of an end of one of the controller bars. Fig. 17 is a section through the set-size index. Fig. 18 is a front sectional elevation about on line F—F of Fig. 11. Fig. 19 is a left sectional elevation about on line G—G. Fig. 20 is a detail of device for preventing action of the pump. Figs. 21 and 22 are details, in section, of the casting pot. Fig. 23 is a front elevation, in section, about on line H—H. Fig.

24 is a detail, showing the impression plunger and a section through a matrix bar. Fig. 25 is a right elevation about on line I—I of Fig. 26. Fig. 26 is a plan of the mold and some adjacent parts. Fig. 27 is a plan 5 detail in section, about on line J—J of Figs. 4 and 13. Fig. 28 is a section on line K—K of Fig. 1. Fig. 29 is a plan detail of the upper line word-space regulator shifting device. Fig. 30 is a section on line L—L of parts shown in Fig. 28. Fig. 31 is a detached view of 10 the shaft and worm to feed the place-finder cylinder. Fig. 32 is a plan detail on line M—M, Fig. 4. Fig. 33 is a detail showing the justifier connection to the body piece limiting stop. Fig. 34 is a detail view of parts 15 connected with the escape shaft. Figs. 35, 36, 37, 38 represent partially diagrammatic, detached parts of the registers and justifier.

General Description.

In order to facilitate the reading and understanding 20 of the detailed description which follows, I will first state the general plan and organization of the type-casting and composing machine which embodies my invention; although, in so doing, I necessarily refer to and describe some features that are old and well known 25 in the art.

I employ a mold and type-injecting mechanism. Above the mold I suspend a matrix case composed of 30 eleven bars, each bar having eleven matrices—the central matrix of the central bar standing normally over the casting point. These bars are arranged around a common center and form a sector of a many-sided, regular, right prism, having a horizontal axis, on or around which they turn. The bars of the case are held together by a suitable frame—the whole being mounted in a matrix-case carriage—to move in the direction of their length bodily, with the carriage. The bars have an independent circular sliding movement on the carriage, which is effected by connections from a rock shaft above the case, which shaft coincides with the axis around which the bars are moved. By rocking this shaft, any desired bar is brought to the central position and by moving the carriage, any desired matrix on a bar is brought to the casting point. A matrix bar, when in the central position, may be 45 moved radially outward to seat the selected matrix on the mold. This movement is accomplished by an impression device which is called into action immediately after the selecting devices have operated. The two movements of the matrix case to select a 50 matrix are effected by a matrix placing mechanism which is operated from a power driven shaft and controlled by pins in an endless belt or chain, which pins are set up or arranged in any desired combination by connections from a finger key-board.

55 I have arranged a set-size index, operated by the connections between the matrix placing mechanism and the matrix-case, to move in unison with the case. This index has pins of varying lengths which represent the sizes, running-wise or set-way, of the corresponding matrices in the case. Connections are made from the index to the body piece to limit the mold opening to correspond with the "set" of the character whose matrix is at the casting point. The pins of the controller having been set, a constantly running 60 power shaft operates, through suitable connections, to

feed the controller to the matrix-placing mechanism; select a matrix corresponding to the pins set in the controller; seat the matrix on the mold; set the body piece; inject type metal into the mold from a casting pot; discharge the cast type and assemble it in a suitable channel or run-way—to be carried finally, to a galley—one type being cast with each revolution of the power shaft and the controller being fed one step each time, so as to cast type and spaces in the order indicated on the controller.

70

75

In the passage of the type from the mold to the galley, I have arranged to project the spaces below the line of type into the path of a saw or cutter, in order to reduce their length. I do this by casting the type and spaces with two nicks and providing the assembly 80 channel with one nick guide and arranging to have the type enter the channel with their lower nick on the guide and to have the spaces driven down so they enter with their upper nick on the guide.

The spaces are driven down from the fact that they 85 are shorter than the type. When a matrix becomes stopped up, the type cast from it is without a head and is short, like a space, and it calls into action a knocking mechanism to drive it down, the same as a space does. Every time the knocker acts, an electric circuit is closed to ring an alarm. When a space is called for by the controller the circuit is broken at another point by a special pin in the controller, so the alarm is not sounded. When the knocker closes the circuit for a short type the circuit is not broken by the controller, 90 as in the case of a space and the alarm sounds, calling the attention of the operator to the fact that a matrix has become clogged.

95

The controller for the matrix placing mechanism is made up of bars or tubes connected together by links and adapted to be carried or fed through the machine over suitable sprocket wheels. The bars or tubes of the controller carry movable pins. These pins are set or driven out by the key action, two pins being ordinarily driven with each stroke of a key—one to select 100 a matrix bar and the other to select the matrix on that bar corresponding to the key struck. The key action also releases an escape shaft which operates to feed the controller one step and to record the width or amount of line space of the character struck, on a suitable register. The divisions of the controller between words are indicated by special space pins and the divisions between lines by special line or galley pins.

105

In order that the operator may find his place on the copy I have arranged to have the machine keep a record, at all times, of the last twenty-five or thirty keys that have been struck. I provide a hollow horizontal cylinder having rows of pins parallel with the axis of the cylinder—one pin for each key. Above the cylinder I arrange an identifying index with the characters of the key-board marked on it. The pins stand normally in an outward position. Connections are made from the key levers so that when a key is struck in the key-board, the cylinder will be turned one step and a pin will be driven down, under the corresponding character marked on the index. By moving the index or turning the cylinder, the operator can read the last few words he has set up on the key-board.

115

A plurality of special controllers or word-space regulators are provided for the justifying spaces. These 120 125 130

consist of blocks having pins which can be set to select spaces of any desired size, each block controlling the spacing for a single line. The setting of these space regulators is effected from a justifier which is brought 5 into action by touching the starting key at the closing of each line—the justifier having received its setting from the registering devices. As already stated, connections from the power shaft feed the controller to the matrix placing mechanism and transfer its settings 10 to the same, selecting the matrices in the same order in which the keys were struck on the key-board. When the bars of the controller representing word spaces are reached, the special space pins of the controller cause the mold body piece to be set from the 15 word-space regulator for that line, instead of from the index; whereby spaces will be cast of proper width to effect the justification of the line, and when one of the line pins is reached a special movement shaft is called into action to draw out the completed line and deposit 20 it in the galley.

General Arrangement of Parts.

A substantially square column is provided, on the top of which, mounted at the left, is the mold and 25 matrix-case. The key-board and place-finder are mounted on the front of the column—the justifying mechanism to the right of the key-board. Just back of the justifier is the controller and beyond it at the right and rear is the matrix-placing mechanism. A shaft 30 and rack, at the top and rear, connect the matrix-placing mechanism to the matrix-case on the left. On these connections is mounted the set-size index. After the type are cast they are carried to the left and brought forward, the line being assembled towards the front. 35 Galley mechanism at the left bring the lines, as completed, still further forward and deposit them towards the right in a galley which is mounted on the front side of the machine, just back of and above the key-board. The column is hollow and its upper back portion is cut 40 away. Across this opening extends the power driven shaft, carrying most of the cams necessary to produce the automatic movements of the machine. The shaft extends to the right, beyond the column and has several cams directly under the matrix placing mechanism. 45 At the left, outside the column, is a vertical spur of the power shaft, carrying cams and a gear to operate some of the mold movements, the type packer and the space cutting saw. A drive pulley is placed at the extreme left. A galley or line shaft, extending through the left 50 side of the column, and driven from the power shaft by a clutch, on the inside of the column, has, on its left hand end, just outside the column, cams and a crank pin to operate the line transfer or galley mechanism. The casting pot is placed at the extreme rear of the column, connection being made to the mold by a long forwardly extending pipe or tube.

Detail Description.

Main frame and drive shafts. The main frame consists of a hollow column 1, substantially square, having a base 2. The upper portion of the column is open at the back. Across this opening is mounted a horizontal shaft 3, held by caps 4 and 5 and driven by power applied to pulley 6, placed at its extreme left end. Outside the column at the left is an auxiliary power shaft

7, mounted vertically and made to turn with the horizontal power shaft by a pair of miter gears 8. These two shafts carry the cams, cranks, gears, etc. necessary to operate the various mechanisms that need to be power driven.

70

A galley shaft 9, mounted inside the column has a bearing at one end in hanger 10. Its other bearing is in the side of the column. This galley shaft is driven by a gear 11, carrying a clutch ratchet 13, loose on the shaft and in mesh with drive gear 12 on the power shaft. A clutch pawl 14, pivoted in shaft 9, is released by connections from a galley pin in the controller, at the proper time, and engages the clutch teeth, causing the shaft to make one revolution to operate the connections to draw out the line and deposit it in the galley. 75 These connections are operated by cams and a crank pin outside of the column.

80

On the top of the column is a bed plate 15. To the column and to this plate are fastened the remaining parts of the frame-work of the machine, which will be 85 pointed out in connection with the parts which they support.

Mold. The mold consists of left and right cheek pieces 16 and 17; body piece 18; cover slide, consisting of upper and lower pieces 19 and 20—the jet chamber 21, being formed in the lower piece 20—the whole being mounted on a mold base 22, which is enclosed between a front bracket 23, and rear bracket 24, on which brackets are mounted the parts which support the matrix-case carriage. The functions and relative arrangements of the mold parts above enumerated are well known—the terms used being the technical ones in common use among type founders.

90

The body piece 18 is normally drawn to rear to open the mold, by a spring 25 secured to the rear end thereof. 100 It is limited in its movements, to correspond to the "set" of various characters, by a stepped stop slide 26, which enters a slot in the body piece—being held, normally, to the left, by spring 27, so as to limit the movement of body piece to a minimum. The body piece is 105 moved positively forward to eject a type, by means of a cam 28, on upper end of shaft 7, acting against a roll 29 on a lever 30.

105

The cover slide is reciprocated to open and close the mold at the proper time, by a connecting rod 31, secured to crank arm 32 on shaft 33, which shaft is mounted in front and rear boxes 34 and 35, being rocked half a revolution to throw the crank to dead centers, by a pinion 36, at the rear end of the shaft, in mesh with a vertical rack 37 which rack is held in place by the cap 110 5 and is operated by a roll 38, entering cam slot 39 of a cam wheel 40. The rack 37 also serves to operate the matrix placing mechanism.

When the cover slide is moved to the right, the jet chamber is in line with a pivoted arm 41, by means of which the jets are ejected—the arm having a connecting rod 42, to a lever 43, operated through roll 44, by cam 45 on the power shaft.

115

The mold has two fixed alining plates 46 and 47, the left one, 46, being cut away on its under side to form a 120 passage way 48, for the head of a type as it is carried away. These alining plates are firmly attached at their rear ends to the stationary cheek pieces 16 and 17 of the mold and at their front ends to an upwardly extending flange of the mold base 22.

125

130

The mold has two nick pieces 49. The cover slide carries a swinging nick guide 50, pivoted at 51—the hole for the pivot being slightly elongated. A spring 52 tends to hold it to the right. When the mold is 5 open, the nick guide 50 is held to align with the upper type nick by reason of a horizontal bolt 53, which acts against an arm 54, said bolt striking a stop 55 on the mold base 22, as the cover slide is drawn to the right by connecting rod 31. In this position the type are 10 free to be ejected by the body piece—the cover slide being drawn back to give a little clearance. As the type are ejected by the body piece they are held by a spring seated arm 56, until the cover slide has started to the left and the spring 52 has caused the guide 50 15 to clamp the type against the end of the cover slide, to hold it while being carried to the left to a type assembly channel 57.

Matrix case and carriage. The matrix case is composed of bars 58, which have plugs 59, of copper or 20 other suitable metal, in which are stamped the type matrices 60. These bars are held together by a four sided frame consisting of side pieces 61 and front and rear curved pieces 62—the bars being slightly loose on pins 63 in the ends 62. The case is carried by a 25 carriage composed of horizontal racks 64, having semi-circular tie pieces 65, braced by under tie plates 66, the matrix bars being supported by ears 67, at either end, resting on the curved tie pieces of the carriage. The carriage racks slide in ways 68 and 69 and the 30 carriage is moved by a pair of gears 70, from a shaft 71 which are in mesh with the carriage racks, the shaft turning in boxes 72 mounted on the ways 68 and 69.

Above the matrix case is a shaft 73, extending from front to rear, parallel with the racks of the matrix-case 35 carriage and having bearings in the front and rear brackets, 23 and 24. This shaft is rocked by the means of a sector gear 91, in mesh with a rack 92, from the matrix-placing mechanism and has a pair of arms 74, to which is fastened a flanged bar 75, which enters 40 notches in the curved ends 62, of the matrix-case frame. By rocking the shaft 73, the matrix carriage can be moved so as to bring any desired matrix bar over the alining slot, between the plates, 46 and 47, at the same time permitting the case to be moved 45 bodily with the carriage. The end pieces 65 of the carriage have notches 76, directly over the alining slot. Normally these notches are filled up flush with the top surface of the end pieces, by toes on the lower end of vertically sliding pieces, 77, each mounted in an 50 elongated slot of an angle bracket 78, carried by the end pieces 65. At their upper ends the pieces 77, have projections which enter slots 79 of an impression bar 80. When the impression bar is in its upper position the toes of pieces 77, fill up the notches in the 55 curved ends of the matrix-case carriage flush with the upper surfaces of said curved ends, permitting any of the matrix bars to pass over them, in the selection of a matrix.

Heretofore in machines of this class it has been customary to arrange the matrices in a flat rectangular form, the matrix-case being required to move over an area substantially four times the area of the case. This arrangement necessitates carrying the type a long distance from the mold or moving it downward, 65 as it is carried away, in order that the matrix-case

may not interfere with the type assembling devices. By arranging the matrix case in curved form, as above described, it occupies or covers less than one-eighth the area used in the former method; permitting me to locate the type-assembling and space-shortening devices but a short distance from the casting point. 70

Matrix-seating or impression device. A matrix having been selected and brought to the impression point, by rocking the matrix-case and moving the carriage bodily, it is seated on the mold at the casting point, 75 by a downward movement of an impression bar 80, which carries a wedge-shaped impression plunger 81, adapted to enter one of a series of notches 82 of the matrix bar, there being a notch 82 for each character upon the matrix bar. 80

The movement of the impression bar is effected by a pair of connecting links 83, to a pair of arms 84, on a shaft 85, mounted in the front and rear brackets and having at its rear end an arm 86, connected by a rod 87, to the outer end of a lever 88, which has a 85 roll 89, on a cam 90, of the power shaft. (This cam and lever is also used to clamp the nipple against the mold, as will be hereafter pointed out.)

With the downward stroke of the impression bar the hooked pieces 77 recede—permitting the plunger 90 81 to seat the matrix bar firmly on the mold. On the return or back stroke of the impression bar, they serve as stripping hooks to positively pull the matrix bar upward, stripping the matrix off the cast type.

The alinement of the matrices on the mold is of very 95 great importance. Heretofore it has been customary, in machines of this class, to either seat a single matrix on the mold in an alining slot, which also serves to give the matrix its "position"—which method gives very little wearing surface; or, to seat the whole matrix-case on the mold—depending on a conical plunger to align and position the matrix. This method gives also very little wearing surface. By my method I have wearing surface practically the entire length of a matrix bar, to bring the matrices into accurate alinement. While the slightest inaccuracy of alinement is noticeable, a slight inaccuracy in the position of the type on the body is not noticeable, and the plunger 81 seats the matrix bar sufficiently accurate to give the matrix its proper "position". In this, too, an 110 increased amount of wearing surface is afforded over the conical plunger heretofore used for the same purpose—the wedge-shaped impression plunger being the full width of a matrix bar. 105

Matrix-placing mechanism. The matrix-placing 115 mechanism is mounted in a four sided frame composed of front 93; left and right sides 94 and 95, upper back plate 96 and lower back plate 97 all fastened together and bolted to the right side of the main column. Within this framework is mounted two vertically sliding 120 frames, the front one, composed of side racks 98, is joined together by a cross tie 99. These racks are in mesh with a pair of gears 100, which are on the shaft 71. By moving this frame up or down the shaft 71 will be rocked and the matrix case carriage moved thereby, 125 either forward or backward. The rear frame is composed of side pieces 101, having a cross tie 102. The left bar has a rack 103, in mesh with the pinion 104, on a shaft 105, which carries a second pinion 106, in mesh with the rack 107, which rack is connected with the 130

rack 92. By moving the rear frame up or down, motion is imparted to rock the matrix-case—swinging it on the shaft 73, to select any of the matrix bars.

At the rear of the frames, just pointed out, there is a series of ten vertical placer slides, 108. These slides are connected together by pins 109, in the second and fourth slides from the right and left hand sides, which enter slots 110 in the next adjacent bars, as shown in Fig. 9. The middle two slides are connected only by pin and slot 590 and 591. The left hand slide 108 has, on its outer side, a rack 111 which is in mesh with a gear 112, on a short shaft 113. This shaft carries a second gear 114, which is in mesh with the vertically reciprocating rack 37, already pointed out. The left hand placer slide has, on its right side, a rack 115, which is connected by a reversing gear 116 (mounted on a shaft 117) to a rack 118, on the right hand placer slide. From these connections, it will be seen that as the rack 37 is reciprocated, the placer slides will alternately take the positions shown in Figs. 7 and 9. In the latter figure they are shown in a uniformly stepped position—half of them having been carried upward uniformly varying distances and half of them having been carried downward uniformly varying distances. The outside slides were each carried five steps. The adjacent slides, as you go towards the center, are each carried one step less, until you reach the middle two, which can be moved only one step each, in opposite directions—their movement being limited by the pin 30 and slot 590 and 591. The two slides which contain the pin and slot 590 and 591, might be limited by pins 108^a entering slots 97^a in the back plate 97, as shown in Fig. 9^a. It is only necessary that the movement of the middle two slides be limited to one step each; that the outside slides be given the greatest throw; and that the intermediate slides be limited and brought to uniformly stepped positions—all slack between the slides being taken up when the slides are either in their home or their set position. The placer slides have two series of holes, 119 and the cross pieces 99 and 102 have each a series of connecting pins 120. In their "home" position, the connecting pins are in line with the corresponding holes 119 of the placer slides. The frames will be carried either upward or downward on the next movement of the placer slides any desired distances, according to the pins 120, which are projected into them—thus securing the selection of any matrix at the impression point. On the return of the slides, the frames are brought back to their starting position and the matrix case returned thereby, to its normal central position over the casting point. The connecting pins projected into the placer slides, are returned by a series of pins 121, carried by said slides which, on the return of the slides, are adapted to be driven forward by a pair of rocking blades 122, mounted between the side plates 91 and 95 and operated by arms 123, from a vertically moving bar 124, which arms strike arms 125 of the blades 122. These blades 122 have upwardly projecting arms 126, which are connected by slot and pin connections to a pair of locking and alining bolts 127, mounted in the side plate 94 and adapted to enter notches in the frames 98 and 101, to accurately position the matrix-placing frames in their home positions. As one of the connecting pins is driven, it strikes against one of the pins 121, driving backward the rocking blade

122 and withdrawing its bolt 127—thereby freeing the frame and permitting it to be carried by one of the placer slides.

The bar 124 is reciprocated by a cam 128 on the power shaft, connection being made by a roll 128^a on lever 70 129—a yielding safety spring 130, being interposed.

Controller. Before proceeding further with the description of the matrix-placing mechanism it will be desirable to describe the controller. This is in the form of an endless belt or chain and is composed of hollow bars or tubes 131, carrying actuating pins 132. These pins can be moved outwardly in the tubes into an active or set position and they are held by spiral or helical friction springs 133. The tubes are connected by links 134, pivoted together by pins 135, which are inserted in the ends of the tubes—the heads of the pins being adapted to engage the teeth of sprocket wheels. The tubes are fastened together in pairs by pins 136, which pins also pass through the pins 135 and serve the double purpose of keeping the pins 135 in place and of preventing the tubes from turning—thereby keeping the actuating pins in a constant position in reference to the general path of movement of the chain. The controller is supported and fed through the setting mechanism by a pair of sprocket wheels 137, which are on a shaft 138. The movement of this shaft is controlled by the finger key action, as will be subsequently pointed out. The controller is supported and fed to the matrix placing mechanism by a pair of sprocket wheels 139, which are on a shaft 140. The shaft 140 is mounted in left and right side brackets 141 and 142 extending forward from the plates 94 and 95 respectively, and is turned to feed the controller to the matrix-placing mechanism by a star wheel 143. The star wheel, which is on the right hand end of the shaft, is engaged by teeth 144 which are mounted on a connecting rod 145. The connecting rod is vibrated by a cam 148 on the power shaft—connection being made to the same by cam lever 146 and roll 147.

The position of the controller in the machine is shown in Fig. 6—a portion of it being indicated by a dotted line. The shafts 138 and 140, as shown in this figure, are turned "clockwise" thereby feeding the controller to the right.

As the tubes of the controller pass over the sprockets 137 and 139, the actuating pins 132 point to the centers of the shafts 138 and 140—the pins of each pair of tubes being slightly at an angle to each other.

The connecting pins 120 are driven into the placer slides 108 by idle plungers 149, which are moved by vertical cam slides 150. These slides have hooks at their upper ends and are adapted to be raised by a set of transfer slides 151, carried in a vertically movable frame 152, to which a vibrating movement is given by means of cam 153, through the following connections: roll 154; lever 155; connecting link 156; slide 156^a—the connection between the lever and link being made a yielding one.

When the frame 152 is in its lower position, the forward ends of the slides 151 come in the path of the actuating pins of the controller, which is moved at that time. If any pins have been set in the controller, corresponding slides 151 will be driven rearward and on raising the frame 152, the vertical cam slides 150, will be raised, thereby forcing corresponding connecting

pins into the plater slides. Half the slides 150 are short and half of them are long, to operate the upper and lower sets of pins 149, respectively. On the downward movement of frame 152, a projecting flange of a keeper 157, returns the vertical cam slides and a rocking blade 158, acting against lugs 158^a, on the under side of slides 151, return them to place—the movement being effected by a bell crank lever 159, mounted on inside of bracket 142 and having a connecting rod 160, to lever 161, which has a roll 162 and is moved by cam 163 on the power shaft.

The odd numbered slides 151, counting from the left, are in one series and operate the short set of cam slides 150. The even numbered slides form another series and operate the long ones. In case two actuating pins in one series should be accidentally set, I have provided a safety device, as follows: Each of the slides 151 has a lug 164. Cords 165 fastened to posts 165^a pass through all the lugs of each series and are attached to the lower end of a lever stop-latch 166, which is mounted on the frame 152. A series of pins or posts 167 are placed in proximity to each of the cords. As a slide is moved to the rear, the cord is drawn between the posts. Sufficient slack is given so that one slide will just draw the cord taut. If more than one slide is driven at one time the pawl 166 will be thrown out and will engage in a notch in a vertical slide 168, mounted in a slot cut in side bracket 141 and an upward projecting horn 169 on the same, and will carry the slide upward a short distance, until it reaches the end of its slot—blocking a further upward movement of the carriage and causing the connection between connecting link 156 and lever 155 to yield. A slight upward movement of piece 168 is permitted, sufficient to close an electric circuit in the wires 170, at the point 171, ringing an alarm bell 172, to call the operator's attention.

The left hand slide 151 is controlled by a galley pin in the controller and is adapted to raise a vertical slide 173, connected by link 174 to a lever 175, on the end of a starting shaft 176, which extends through the side of the column and has a bearing in a downwardly projecting ear of the hanger 10 of galley shaft. When a galley pin is reached in the controller, the upward movement of frame 152, rocks the shaft 176, calling into action the galley shaft, as will be explained later.

The feed or movement of the controller over the sprocket wheels 137 is irregularly intermittent—depending on the action of the finger keys. The movement of the controller, when in action, over sprockets 139, is regular—being fed one step on each revolution of the power shaft, 3. As the keys are operated in the key-board, the controller forms a varying loop between the sprockets 137 and 139—depending on the distance the operator gets ahead of the matrix-placing and casting mechanism. When the operator stops, the controller continues to be fed to the right over the sprockets 139, until it is stopped by reason of the controller striking a pin 177, in the end of an elbow lever 178. This pin is in the path of the controller and as the loop between the sprocket wheels of the two shafts 138 and 140 shortens or straightens, it raises the pin and draws over a slotted connecting rod 179, permitting a pawl 180, to engage a notch in the connecting rod 145, when the latter is in its highest position—thereby stopping the feed of the controller until slack is given it

from the setting devices, by striking additional keys on the key-board. When this is done, a spring 181 draws down the lever arm of elbow lever 178, disengaging the pawl 180 and permitting a spring 182 to draw down the lever 146 and the feed connecting rod 145, again starting the feed of the controller to the matrix placing mechanism. The parts are so timed by the cams that the controller is stopped when the matrix placing frames and matrix case are in their home or normal positions, in which positions connections are made to prevent the action of the metal injecting pump, as will be hereafter pointed out.

Set-size index. In order to set the body piece of the mold to cast a type corresponding to the character whose matrix is at the casting point, I employ a set-size index. This consists of a cylinder 183 mounted for sliding movement on a squared section of the shaft 71 and inclosed between two arms 184 from the rack 92. On this cylinder I arrange eleven rows of fixed projecting pins 185 with eleven pins in each row, corresponding to the matrices of the "case". There are as many different lengths of pins as there are different sizes (running-wise or set-way) of type to be cast. It will be seen from the construction shown, that the index has a movement corresponding to that of the matrix-case—it being controlled by the two connections from the matrix placing mechanism. After the case has been located to select a matrix, a bar 186 is thrust yieldingly against the selected pin of the index. This is done from a cam surface 187 on the wheel 40, through the following parts: roll 188, arm 189; spring 190; arm 191; connecting link 192. The two arms are pivoted to a hanger 193, fastened to the inside of the column and the spring 190 serves to make the movement yielding. The bar 186 is mounted in bed plate 15 and near its lower end it is guided by a flanged collar on one of the rods *d*, which extend between the front and rear sides of the column. Connection is made from the bar 186 to the stepped limiting stop 26 for the body piece by a connecting rod *f*, having a hooked end *g*, engaging a hook *h* of the stop piece, and pivoted to an upward arm of a bell crank lever *i* fulcrumed to a block 194 on the bed plate 15—the lever having a lower horizontal arm adapted to engage a pin 195 in the bar 186. After a matrix has been selected, the bar, through the connections pointed out, sets the body piece to cast a type corresponding in thickness to the selected matrix.

The steps on the limiting stop 26 represent half units, as will be hereafter explained, and the hook *h* has two steps. By raising the end of the connecting rod *f*, the body piece 18 of the mold will take its setting on the next adjacent step on the limiting stop 26 from that called for by the stop pin of the index, and a type or space will be cast half a unit smaller or thinner than the indicated size on the index. The purpose of this will be explained in describing the justifying mechanism.

The hooked connection between stepped stop and the connecting rod, permits the withdrawing of the bar 186 and the returning of the matrix-case to normal or starting position, without interfering with the setting of the body piece, thereby giving more time for the type to cool.

One method heretofore employed in machines of this class has been to indicate the set-size of the character on the controller. This necessitates additional connec-

tions from the key-board and makes the controller unduly wide, especially where there are a large number of sizes used. It has, however, the advantage of permitting the matrices to be arranged in the case in any desired order, so that those frequently used can be located where they will have to be moved but a short distance in order to locate them at the casting point. Another method that has been employed has been to group characters of the same width into sections or rows in the matrix-case—connections being made to limit the body piece for a given size when any row or section is over the casting point. This method does not widen the controller but, in this arbitrary arrangement, some letters frequently used are placed where they require a long movement of the matrix case, while some matrices seldom used require but a short movement of the matrix case, in order to locate them at the casting point. By using the set-size index as above described, I gain the advantages of both the other methods.

Key-board and pin-setting devices. The key mechanism and connections to set the controller pins 132 are mounted on a base plate 196 supported by a bracket 197 on the front side of the column. The frame-work for the same consists of left and right key-box sides 198 and 199 with stepped piece 200, for the finger keys. At the back edge, close to the column, there is a rectangular box, composed of side plates 201 and 202 and ends 203 and 204. These plates extend to the right beyond the base plate. The right hand end piece 204 and an intermediate blocking piece 205 extend upward to support the controller as it passes over the setting feed sprockets 137 on shaft 138, already pointed out.

Directly under the bar or tube 131 of the controller which is at the top of the sprocket wheels 137 there is a series of vertical setting plungers 206—one for every pin of a controller bar. These setting plungers are held near their upper ends in a slotted cross bar 207 having cap piece 208. At their lower ends they are attached by short arms 209 to rock shafts 210. These rock shafts with the exception of the short top one, (see Fig. 18) are pivoted at their left ends, in the end piece 203 of the box frame-work, and at their right hand ends in a piece 211 fastened to the back plate 202. Connections from the finger keys 212 to rock these shafts and thereby drive corresponding pins in the controller are made as follows: Each key 212 is connected by a stem 213 to a horizontal key lever 214 fulcrumed at 215 and having at its rear end a vertical driving or hammer bar 216. These bars are guided at their upper ends by tongues entering slots 217 of a spreader rail 218 attached to back plate 202. At their lower ends they are slotted and straddle the key lever, being supported by pins 219 entering slots 220 of the key levers. The hammer bars have lugs 221 which are adapted to strike against arms 222 in the rock shafts 210. The key action is limited by a common bar or bail 223, which is adapted to be raised by each of the key levers. This bar is attached by end links 224 to arms 225 on a rock shaft 226 mounted on the base plate 196, so that a key lever can raise the hammer slides, by positive action only, until the lugs 221 just come up to the arms 222 of the rock shafts. By giving the keys a quick, staccato stroke, the hammer slides are carried upward, by their momentum or inertia, be-

yond the point to which they are raised positively, causing the lugs 221 to rock one or more of the shafts and setting corresponding pins in the controller. The upward movement of bail 223 trips an escape shaft 227 having a rear bearing in plate 202 and a front bearing 70 in a bracket 290 and connected by a pair of miter gears 228 and 229 to a vertical shaft 230. This vertical shaft has, on its upper end, a worm 231, in mesh with a gear 232 on the left hand end of sprocket shaft 138, by means of which the controller is fed so as to bring the next adjacent bar to the setting point. The actuating pins are returned before they reach this point by a roll r , which is located as shown in Fig. 6. The tubes 131 just clear it, but any projecting pins are driven down by it. The rock shafts 210 are positively returned and their corresponding pin-setting plungers 206 withdrawn so as to insure their being out of the way of the next row of unset pins, as the controller is fed, by a cam 233 on the vertical shaft 230 driving down a slide 234. This returning slide has lugs 235 one for each rock shaft and is 85 adapted to return the entire series of rock shafts. The hammer slides are also returned, the amount of their extra or inertia movement; but there is no back thump on the key in case the finger is held down until the shaft completes its revolution. 90

The escape shaft has, in its rear end, a pivoted clutch pawl 236, adapted to engage a drive ratchet 237 on the forward end of shaft 238 which is mounted in a hanger 239 on the right hand side of the column. The shaft 238 is driven through gears 240 and 241, shaft 242, pulley 243, by a belt 244 from a pulley 245 on the power shaft. The clutch pawl is normally held out of engagement by an arm 246 having a wedge-shaped end 247 and mounted on a shaft 248 in the back plate. This shaft has, on its forward end, in a recess 249 in back plate, an 100 arm 250. On striking a key the bail 223 is raised and a connecting rod 251, having a pin 252 in contact with the bail, is raised and, through the parts pointed out, the escape shaft is put in motion. A throw-off bar 253 is driven over from a flattened side of the hub of gear 228, 105 carrying the trip rod from under the end of its arm and permitting a branch 254 of arm 246 being driven outward by cam 255 and bringing the stop wedge into position to intercept the clutch pawl.

A spring 256 attached to the trip rod acts through the bail 223, to return the keys to position, when released by the fingers. 110

The right hand pin in each of the controller bars is a special circuit-breaking or throw-off pin for an alarm device. It is set whenever a fixed-space key is struck 115 in the key-board—all the fixed-space keys being near the right hand side of the key-board where they will operate on the upper rock shaft 210.

The second pin from the right is a special word space pin and is set from the space key or bar 257 to call into 120 action the necessary mechanism to secure justifying spaces. Its setting plunger has a lug 258 adapted to engage a similar lug 259 of the right hand setting plunger, to raise the latter whenever the space bar is struck.

The left hand pin of the controller bars is the line or 125 galley pin. It is set by a connecting rod 260 attached to an arm 261 on a short shaft 262 mounted by hanger 263 on the rear plate and having an arm 264 in position to be struck by a pin 265 in a slide 266, which slide is mounted on the right hand side piece of key-board box 130

and is driven rearward by connections from a starting key.

Place finder. This device, already referred to, consists of a hollow cylinder 267, mounted between left 5 and right hand brackets 268 and 279 on three rolls 270 at either end—the end brackets being attached to a base plate 271 which rests on top of the key-box side pieces. In the cylinder are mounted rows of friction-held pins 272 standing normally in an outward position—each row (length-wise the cylinder) containing a pin for every key of the key-board and having the corresponding characters marked on the front surfaces of an identifying index 273, which extends the whole length of the key-board. This index is mounted, at its 10 left end, to an arm 274, pivoted at the axis of the cylinder and at its right hand end, to an arm 275 attached to a ring 276 loose on the cylinder. Just back of the cylinder is a series of angle levers 277 having, at their upper ends, pivoted pawls 278, held normally to position 15 shown in Fig. 11, by springs 279. Between the rear ends of the single levers and their corresponding key levers, there are vertical plungers 280, mounted to slide in a pair of plates 281. The cylinder has, at its right hand end, a gear 282 in mesh with a worm 283 20 carried by a shaft 284, mounted on a vertical slide 285 held by keepers 286 on the right hand bracket 269. This shaft is in line with the escape shaft and is made to turn with it by means of slotted arm 287 engaging a pin 288 in a disk 289 at the forward end and just outside 25 the supporting bracket 290 of the escape shaft. With each stroke of a key, a pin corresponding to the character struck, will be driven down by one of the pawls 278 and, on the movement of the escape shaft, through the parts pointed out, the cylinder will be revolved 30 one step and the driven pin will stand under the identifying index, opposite or adjacent to the printed character marked thereon. This makes a record of the order in which the keys are struck. The pins are driven out just before they reach the setting point, by 35 a roll 291, extending the whole length of the cylinder and mounted between arms 292 to a shaft 293, which shaft has, on its right hand end, a lever 294. The front arm of the lever is flexible sidewise and has a hole engag- 40 gaging a pin 295 in the end of a bracket 296 from the side of the key box. These connections hold the roll 291 locked against the inside surface of the cylinder, to drive out the pins. The rear arm of lever 294 eng- 45 gages a pin 297 in the slide 285. By springing the end of lever off the pin and depressing it until the pin enters 50 a hole 298 the roll 291 is drawn away from the cylinder and the worm freed from its gear. This permits the cylinder to be freely turned, without driving back or returning any of the pins which have been set, in order to bring any row of pins under the identifying 55 index to read the recorded character. The last four or five characters can be read without moving any of the parts and the index can be swung round on its pivoted mountings to cover several more rows. This, ordinarily, is all that is needed; but, when it is desired 60 to read the record of the pins on the under side of the cylinder, the cylinder can be released and turned as stated without destroying its record.

Unit register. As each key is struck in the key-board, the width or amount of space that a character would 65 occupy in a line is registered on a scale 299 by a pointer

300, on the front end of a shaft 301, mounted in a hanger 302 and carrying at its rear end, a ratchet wheel 303. Each tooth of the ratchet represents a justifying unit which, in the machine illustrated, I have assumed to be one-seventh of the type body. I arrange, however, 70 to register fractional units, as one-half, one-third, one-quarter, etc. This makes the unit that I may use in casting type widths very much smaller. I have illustrated a mechanism for registering half units. This makes the real available unit, that I may use in casting 75 type, one-half that size, or one-fourteenth the body size of the type and the pins on the set-size index are made to correspond with these half units. In the illustrations I assume the thinnest letter or character to be three units and the thickest to be seven; or an 80 even em.

The ratchet wheel 303 is fed by a pawl 304 attached to a slide 305, mounted in the edge of an opening in the front plate 201. It is retained by a pawl 306 mounted on a rocking and releasing slide 307, against the action 85 of a weight (not shown) attached to a cord 308 which passes around a sheave 309 on shaft 301. The slide 305 is connected by rod 310, to a crank pin 311 on the under face of gear 229 and has an elongated slot, 312. With each revolution of the escape shaft a spring 313 tends 90 to draw the slide to the left to give the feed pawl its full throw to register seven units. By limiting the slide I am able to record a less number of units. I do this by interposing one of five limiting stops 314. These stops are pivoted at their bottom ends to horizontal levers 315, mounted on the front side of plate 201 which have springs 316 tending to cause the limiting stops to move upward to seek engagement with the slide. They are prevented from so moving by shouldered latch bolts 317, which extend through plate 201. 100 and are held in position by springs 318. On the back side of plate 201 there are mounted six rock shafts 319 similar to rock shafts 210. The lower five of these have arms 320 opposite the latches 317. These shafts are rocked by lugs 321 in the front edges of the hammer 105 slides, in precisely the same manner as the shafts 210 are rocked, by striking keys on the key-board. The rocking movements of shaft 319 release or unlatch the limiting stops 314 and the movement from the escape shaft, called into action by touching the key, registers 110 110 the width of the character struck, on the dial,—provided that character is represented by a whole or integral unit.

I arrange to register the half units in the following manner: The limiting stops being pivoted at their bottom ends, are capable of a swinging movement to the left. Normally they are backed up and prevented from swinging by a stop arm 322 which is pivoted to plate 201. Mounted on the same pivot or fulcrum is a swinging lever 323 adapted to be moved upward by a 120 ratchet pawl 324, attached to a lever 325 similar to the levers 315 and released in the same manner by the upper rock shaft 319. There are two feed notches or teeth on the lever 323 and there is a retaining pawl 326 for it pivoted to plate 201. 125

The hammer slides of all the key levers for characters represented by half units are made to rock the upper one of the shafts 319. The first character having a half unit to register will have its whole or integral units registered on the wheel and the lever 323 will be moved 130

upward one notch, when a pin 327 carried by said lever will be in contact with arm 322. The second character having a half unit to register, will cause the lever 323 to raise the arm, thereby releasing the limiting stops and 5 permitting them to be carried bodily to the left; whereby the limiting stop called into action, instead of registering its normal integral units, will register one unit more. As the limiting stops are carried to the left, the left hand stop strikes a pin 328 in a movable bar 329, 10 carrying it to the left until it strikes the feed and retaining pawls for lever 323 thereby releasing the lever and permitting it to fall to its starting or zero position.

By providing the lever 323 with three teeth I can register third units; four teeth, quarter units etc. In order 15 to prevent it from operating on the register in case the escape shaft should be accidentally called into action, I provide a locking latch 330. As one of the limiting stops is raised, this latch is lifted out of the way. The latch has an upwardly extending arm 331 connected by

20 link 332 to a lever 333. A cam 334 on hub of gear 239 acting through these parts, returns the latch to position after the feed pawl has completed its registering movement, and also returns the limiting stops to their latched positions, as well as the fractional or half unit 25 feed pawl 324 the latter movement being effected by a branch 335 of lever 325 to a pin 336 in the latch 330.

Pivoted to the lever 323 is a connecting link 337 attached to an arm 338 on a shaft 339. The purpose of this is to show when an odd half unit is left over with 30 out being added to the registering wheel, as will be explained in describing the justifier.

In its starting or zero position the ratchet wheel 303 has a stop block 340, resting against the end of an arm 341 which arm is pivoted to the banger 302. A pin 342 35 in the arm 341 is engaged by a spiral 343, carrying the arm 341 out of the path of the stop 340, thereby permitting the ratchet wheel to make more than one revolution, but bringing the arm back to intercept the block on its return to zero position.

40 *Line word-space regulators.* At the right of the keyboard there is a long rectangular support 344, fastened, at its upper end to plate 201 and at its lower end, by a bracket 345, to the main column, in and on which are mounted the justifier and the line-word space regulators. These regulators are set by the justifier and 45 afterward come into effect to regulate the spacing, to justify the lines—one regulator being set for each corresponding line section of the controller and being held in reserve until that corresponding section of the controller is called into use. In the drawings I have shown seven of these regulators. These regulators consist of rectangular blocks 346 having pins 347—each block being adapted to regulate the spacing for a single line.

55 These are as many horizontal rows of the pins, as there are possible justifying spaces in a line. (In the drawings I have shown seven.) The vertical rows represent different sizes of spaces—four such rows being shown. These blocks are arranged to circulate, being 60 used over and over again. They pass down a channel or run-way 348 and are carried backward to a rear channel 349 in which they are elevated and from which they are carried forward at the top and dropped into the descending run-way. At the start, these blocks 65 are all in the upper or magazine portion of the front

channel, where they are held by an escapement pawl 350, with their pins standing in a forward position. After a line has been set up on the key-board, the lowermost block is released, the justifier drives certain of the pins rearward, as will be hereafter explained, and 70 the block passes on to the bottom of the channel. When in this position, a plunger rack 351, is thrust yieldingly against the projected pins, successive horizontal rows being taken each time a word space is reached—the mechanism which operates it being called into action 75 by the space pin in the controller. These connections and the connections to the set-size index bar will now be pointed out. The plunger 351 is carried in a cross head 352 on a vertically movable rack 353, mounted in lower left side of frame 344. It is given an upward 80 movement, step by step, by means of a feed pawl 354, on a bell crank lever 355, and held in the different positions set, by a retaining pawl 356—the rack having teeth 357 for engagement with the pawls.

The plunger rack engages an elongated pinion 358 85 which is mounted on the bracket 345, and is adapted to move the rack when the latter is in any of its positions. Motion is imparted to the pinion 358 by a horizontal rack 359 in the upper edge of bracket 345. This bracket has a projecting flange 360 in which is mounted a transverse rack 361, connected by a gear 362 to the rack 359. The rack 361 receives its motion from a vertical rack 363 to which it is connected by a pair of gears 364 and 365 on a short shaft 365 mounted in the bracket 360. This vertical rack is drawn upward by a bar 366 90 having a hooked upper end similar to the slides 150, and is adapted to be operated in the same manner by the right hand slide 151; which is controlled by the special space pins. A yielding connection is made between slide 366, and rack 363 by a spring 367—the 100 screw connecting the two pieces working in an elongated hole or slot.

From the above construction it is evident that, when a space pin is reached in the controller, the plunger 351 will be thrust against a projected pin of the regulator and 105 will have a greater or less movement, according to the pin set. On the return of the parts to their normal position, a pin 390 in rack 359 strikes against lower arm of bell crank 355 feeding the rack 353 upward one notch.

The transverse horizontal rack 361 extends to the 110 left through the side of the column and has a toe 368, adapted to engage a stepped piece 369 on the lower end of the set-size index bar.

As previously stated, when the matrix case is in position to cast justifying spaces, the set-size index will 115 not limit the bar 186. At this time the toe 368 on the rack 361 comes into play to limit the upward movement of the bar to set the body piece to cast the size space that is indicated in the regulator block.

When a galley pin is reached in the controller, the 120 lever 173 is operated, as already explained. On the front end of this lever is a sector gear 370 in mesh with a sector 371 on a shaft 372 in frame 344, by means of which the said shaft is rocked, causing an arm 373 to strike the upper end of a lever 374, driving rearward a pin 375, releasing the feed and retaining pawls 354 and 356 respectively and permitting rack 353 to return to its lowest or starting position.

The line-word-space regulator, from which the settings have just been taken is carried to the rear by a 130

pusher plate 376 attached to a rack 377, mounted in a keeper 378 and driven by a gear 379 in mesh with it and with a vertical rack 380, mounted on the right hand side of frame 344 and operated by a gear 381, on the right hand end of the shaft 372. As it reaches its rear position, it is brought into engagement with feed pawls 382 which is carried by a vibrating bar 383 and fed, step by step, from one pawl to another until it reaches the top—being retained at each step by sliding pin or plunger latches 384 which are mounted in the right hand side of the support 344 and held in position by springs 385. Motion is imparted to the bar 383 from a crank pin 386, acting through connecting rod 387 and lever 388, said lever being fulcrumed to the horn 360 of bracket 345 and connected by pin 389 to the bar 383. At the same time that a regulator is carried rearward, the one previously used which, by this time, has reached the top of channel 349, is carried forward, by a plate 391, attached to a rack 392 mounted in a keeper 393 and connected by a gear 394 in mesh with the said rack and the vertical rack 380. As the regulator is carried rearward the pins which have been set strike against the vibrating bar and the back side of the runway, driving them forward to their normal or unset position—the first upward movement of a regulator being given by a shoulder 395 on the vibrating bar. The timing of the cams in reference to the crank pin is such that a regulator reaches its rearmost movement when the vibrator is at the lowest part of its stroke and the shoulder 395 is below the regulator.

Justifier. The justifier is an improved form of a similar device shown and described in English Patent No. 2344 of 1891, to F. A. Johnson, and W. E. Crane, and operates on the quotient-and-remainder principle. That is, the total amount of space represented in units to be added to a line is divided by the number of word spaces in the line. If the quotient comes out even, word spaces of even size are selected throughout the line. If there is a remainder, it is apportioned among the spaces as far as it will go—the remaining spaces being the integral quotient. A complete justifier, as embodied in my improved form will now be described. The sizes of the spaces that can be cast and the number of justifying spaces that can be put in a line are fixed arbitrarily. The amount of space that may be added to any line is, therefore, limited to the range determined upon. To illustrate the principles, I have shown in the machine illustrated, provision for seven justifying spaces in a line and different sizes of spaces varying from three units in thickness for the smallest to seven units for the largest—three units being considered as the normal space. If there is only one space in a line, four units can be added. If there are seven word spaces in a line, twenty eight units can be added. The amount of space that may be added depends, also, on the size of units adopted. If a large unit is adopted the number of positions in which the justifier has to be set to cover all possible combinations within a fixed range are few; while with a small unit, a very much larger number of combinations are necessary. Heretofore, when a large unit was used as the basis for justification, the same size unit has had to be used in casting the type characters. This necessitates using what is known as "self-spacing" type. By my improve-

ments, I am able to use a large unit in the justifier and a smaller one in casting the type. This enables me to practically duplicate any face of type. The relative sizes of the unit may be fixed at any convenient ratio as one-half, one third, one quarter, etc. I have illustrated and will describe a construction in which the type unit is one half the size of the justifying unit—the registering mechanism already described, being adapted to register such half units.

In registering the amount of line space the characters on the key-board will occupy in a line, the record of type widths is made on the register in terms of the justifying unit—the half units necessary being added in on the register wheel every time that two of them are counted. The units indicated by the set-size index are the real type units, *i. e.*, one-half the justifying units.

It makes no difference whether the justifying unit be taken as the standard and the type unit be considered as fractional; or whether the type unit be taken for the standard and the justifying unit be considered a multiple thereof. The important feature to remember is, that by eliminating an odd unit or fractional remainder from the amount of space registered by the unit register, the amount of extra units to be added to the line to effect justification, will always be a multiple of the justifying unit. The justifying mechanism comprises a means for eliminating this odd or fractional unit, by reducing one of the word spaces independent of the setting and action of the other parts of the justifier. If the type unit were made one-third of the justifying unit, there might be $\frac{1}{3}$ or $\frac{2}{3}$ of a unit left over on the register. In such a case the independent mechanism of the justifying device would need to be arranged to eliminate the fractional remainder by reducing either one or two of the word-spaces, according as there was $\frac{1}{3}$ or $\frac{2}{3}$ of a unit to be eliminated—and so on for other ratios. In order to illustrate the principle, I will, as before stated, show and describe a mechanism in which the type unit is one-half the justifying unit.

By eliminating an odd half unit, if there is one left over in the registering mechanism, connections can be made direct from the register to the justifier on the basis of the large or justifying unit. When there is an odd half unit left over I arrange to drive a special pin 396 in the line word-space regulators, as will be pointed out later. This pin operates to reduce the first justifying space cast—making it half a unit smaller than the setting given it by the regulator. This is effected in the following manner: The plunger 351 carries, in its left end, a contact or circuit closing pin 397. When the first justifying space of a line is reached, the plunger 351 is drawn to the right, causing pin 397 to close an electric circuit in the wires 398 by making contact with springs 399. Normally this circuit is open between two spring contact pieces 400. If the odd half unit pin is set in a regulator, it will, when in its lowest or active position, strike against the end of a lever 401, causing it to make contact between the springs 400. The circuit is now complete and battery 402 will energize an electro magnet 403. The armature lever 404 of this magnet has pivoted to it a connecting rod 405, which is guided in a hollow tube 406 through the bed plate 15, and is in contact, at its upper end, with the

hooked connecting rod δ ; thereby raising the same and reducing the set-size of the body piece half a unit as already stated. If the odd half unit pin is not set, the magnet is not energized and no change is made in the setting for a justifying space. The plunger 351 being carried upward at each stroke, the contact pin 397 moving therewith away from the contact spring 399, can be called into action only once for each line.

The justifier proper, consists of four frames 407 the 10 left hand one being mounted to slide in the support 344 and the three others mounted in racks 409 adapted to be moved vertically and to have a sliding movement on the racks. These frames are immediately before the front or descending run-way for the line word-space 15 regulators, each frame being in line with and adapted to drive one of the four vertical rows of pins of the regulators. By moving the racks varying distances, and by positioning a line word-space regulator at varying points, the pins can be set in any desired combination to effect 20 the justification of a line. The position of the regulator, when it receives its setting, depends on the amount of line space registered and is controlled by connections from the register. The frames are positioned by connections from a word-space counter.

25 The racks 409 are in mesh with pinions 410 on a shaft 411. A cord 412 to which is attached a weight 413, acting through a sheave 414 on shaft 411, tends to keep the racks all in an upward or starting position, so that the frames 407 are in line. The right hand rack has a 30 ratchet rack 415 and is fed downward one tooth every time the word space key is struck in the key-board, by a feed pawl 416 on end of an elbow lever 417. This lever is latched by bolt 418 against the action of a spring 419. Pivoted on the same fulcrum as the lever, is an 35 arm 420 having a roll 421 in contact with the eccentric 289. This arm has a pin 422 which, when it is raised returns the lever 417 to its latched position. The arm 420 vibrates with every revolution of the escape shaft. The rock shaft 210 used to set the special space pin in 40 the controller, has an arm 423 which engages in a notch of the bolt 418, and on striking the word space key the bolt is withdrawn, unlatching the lever 417 and permitting the pawl to take a tooth to feed the racks downward. A retaining pawl 424 (Fig. 2,) holds the racks in 45 place during the back stroke of feed pawl 416.

The gears 410 vary in size so that the racks are opened up in uniformly varying steps—the first movable frame being carried a distance equal to the space between two horizontal rows of pins in the regulators. The second 50 one is carried twice that distance and the third one three times as far, every time a word space is registered. The movements represent an arithmetical progression and the frames vary at all times by uniform steps—corresponding to the number of word spaces in a line.

55 Connections are made from the unit register to position the height of the regulators, as follows: The shaft 301 of the unit register has a sector 425, loosely mounted thereon, in mesh with a vertical rack 426. This rack has, at its bottom end, a sliding bolt 427, which is 60 adapted to enter the descending runway of the regulators, to intercept a regulator and carry it upward, leaving it, on the completion of a line on the key-board, in varying heights opposite the justifier frames 407—according to the total amount of units registered.

When the register has reached a point within the 65 range of justification, a tooth 428 on a disk 429 carried by an arm 430 on the register shaft (adjustment being made by screw 431 in holes 432) strikes against a toothed wheel 433 mounted on the sector and thereafter the sector turns with the register shaft. The teeth of wheel 70 433 can be set so the shaft 301 will make one, two or more revolutions before picking up the sector (a movement quite similar to the well known Geneva stop.) by which, in connection with the adjustment in the holes 75 432, the length of line may be varied as desired.

The action of the justifier may now be explained by a few concrete examples.

Suppose that seven spaces have been registered from the key-board and that there is nothing to add—the total line space just coming out even with the amount 80 required for a line. In this case the sector will have drawn up the rack 426 and the regulator will stand so that its left hand row of pins is directly behind the first or left hand justifier frame, and the racks will be opened up their full movements, leaving the regulator and 85 justifier frames in relative position shown in Fig. 37. On touching the starting key, the justifier frames are moved backward by a setting plate 434 connected by angle bracket 435 to the slide 266 on right hand side of key box and the pins of the regulator opposite the justifier frames are driven rearward. In the position shown in Fig. 37 the normal or 3-unit row of pins will be driven. In every case where there are no units to add the regulator will always be in this position and will be set to limit the connections to secure the selection of a 3-unit 95 justifying space, which is the size needed to properly space or justify such a line. From an inspection of the diagram, Fig. 37, it will be seen that in case the register had shown one unit short, that the regulator would have been left one step lower and the lowermost pin of the 100 second row in the regulator would have been driven and the first justifying space selected would be a 4-unit space, and the rest would be 3-units each. In case the line was seven units short, the regulator would stand seven steps lower than shown and the second row of 105 pins of the regulator would be driven, selecting seven 4-unit spaces—thus adding the seven units necessary to justify the line. With fourteen units to add, the third row of pins would be driven selecting all 5-unit spaces, and so on—intermediate positions would secure spaces 110 of two different sizes. Fig. 38 shows the relative position of the justifier frames and a regulator when there are four units to add and three word spaces. The first justifying space will be a 5-unit and the next two 4-unit—the first adding two units and the next two one 115 unit each, making the four units necessary to justify the line. In case there were twelve units to add, the regulator would stand with the bottom of the right hand justifier frame on the fourth pin from the bottom. While in this position some of the pins would be driven 120 on touching the starting key, none of the pins driven would be called into action, they being all above the third row from the bottom, and the plunger 351 would not be limited by any of the stops 347, but would take its extreme throw and set the mold to cast 7-unit 125 spaces—adding the twelve units necessary, which would be the maximum amount that could be added with this number of word spaces. It will be seen that,

for any combination within the range of justification, the parts will be positioned by the movements from the two registers, to properly set the pins of the regulator, to secure the selection of the necessary pins to regulate 5 the spacing to justify the line.

Starting key, settings-transfer and releasing devices. The starting key or handle 436 is attached to lever 437 fulcrumed on right hand side of the key box to a short shaft 438. The rear end of the lever has a pivoted arm 439 adapted to strike a roll 440 in the slide 266. On depressing the starting key, the slide is driven rearward; but as soon as the key reaches its full stroke the arm 439 has passed above the roll at which time a spring 441 will immediately draw the slide forward. 10 On releasing the starting key the pivoted end swings out of the path of roll and again drops into place. The object of this is to effect the setting of the regulator pins before the registers are released, which releasing movement is completed by the last part of the stroke of the 15 starting key, as follows: The shaft 438 extends through the side of the key box and has on its inner end an elbow lever 442 one arm of which has a slot and pin connection with a lever 443 mounted at the right, along side of the key levers 214 and similar to them. The 20 other arm of elbow lever engages a pin 444 of a locking bolt 445 mounted in end plate 199 of the key box and which holds the pawl carrying slide 307 locked in its upward position. The movement of the starting key withdraws this bolt. A connecting link 446 attached 25 to rear end of lever 443 has a reversing lever 447 engaging a notch in the side of slide 307 and thereby draws it down, releasing the two register pawls—the retaining pawl being mounted on the slide and the feed pawl being drawn down by a pin 448 in upper end or horn of the 30 slide. The right hand end of slide bar 329 rests in a notch or recess in the slide 307 and is cammed out of its seat and driven to the left, as the said slide is forced down, thereby freeing the fractional unit register of any remainder that may be left in it. A sliding bar 449 at the 35 right is driven out of a similar notch or recess in the right hand side of slide 307 and a forwardly projecting arm 450 on end of said bar, engages the feed and retaining pawls of the word space register and releases them, permitting the racks to return to their upper or zero position. 40 As the unit register is released, the sector drops with its rack 426 to lowermost position, in which position the bolt 427 is withdrawn by cam or wedge piece 451, which is mounted in the support 344 permitting the regulator to pass on toward the bottom of the runway. The extreme downward movement of rack 426 45 operates the escapement pawl 350, a pin 452 entering notch in the pawl as shown in Fig. 35. This releases one of the regulators that stand above and allows it to be caught on lower toe 453 of the pawl. On the first 50 upward movement of the rack the pawl is thrown over, its upper toe 454 entering in a cut-way corner of the regulators, sustaining all the regulators that may be in waiting except the lowermost, which is released and permitted to fall to the dotted position shown at 455 in Fig. 35, where it is caught by the bolt 427. 55 As the releasing slide 307 is drawn down it is held by a latch 456 pivoted to hanger 290 (Fig. 13), which engages a lug 457 on the slide. This gives the registers ample time to return to their zero or starting positions. 60 When the first key for the next line is struck, an arm

458 on bail shaft 226, strikes the latch 456, releasing slide 307 and permitting a spring 459 to raise it to position where it is again locked by bolt 445.

The rear end of lever 443 strikes a trip lever 460, pivoted to rear plate 202, one end of which raises connecting rod 251 and trips the escapement, thereby feeding the controller one step, a galley pin having been set, as previously described, by movement of slide 266—this movement of the controller being necessary before beginning the next line. 70

The fractional unit pin 396 is driven, in case there is a fractional remainder, by a yoke 461 which is carried by two arms 464 on a vertical shaft 465, mounted in frame 344 which yoke is adapted to drive the pin whenever the regulator is in position to receive its setting from the justifier. It is called into action by an interponent rod 462, suspended from an arm 463 attached to the shaft 339, which is connected to the fraction recording parts of the unit register, as already explained. A fractional unit being left over, the lower 80 end of the interponent 462 comes in the path of the plate 434 and is carried rearward with it, on touching the starting key, thereby rocking the shaft 465 and carrying the yoke 461 rearward and setting the fractional unit pin. 85

Casting pot, pump etc. As the matrices are selected and brought to the casting point, successively, in the order that the keys were struck in the key-board, in the manner described, metal is injected into the mold from the casting pot 466, by a pump 467 of old and well known construction, having plunger, valve stem 468, operated by lever 469 fulcrumed at the left by a link 470 to the pot and having at its right end a pump rod 471, to which is attached an actuating spring 472. From the pump well 473, communication is had to the 90 mold by passage way 474 through pipe 475, head 476 and nipple 477—contact with the mold being made through the usual conical nipple and apron method. The apron 478 is made circular and held in place by a handle 479 attached to the under side of the bed 10. The nipple has a slight movement to and from the apron by means of connecting rod 480 operated by the lever 88 already pointed out. The pot is mounted in a casing 481 pivoted at 482 to two long supporting legs 483 connected by tie rods 484 and pivoted at their bottom 105 ends to a pair of arms 485 from a rock shaft 486 mounted in the column and which has an outside lever 487, held in place by pin 488. By swinging the connecting rod 480 away from the lever 88 and removing the pin 488 the whole casting mechanism may be lowered and swung 110 back away from the machine—the pump rod 471 being first thrown off its actuating or cam lever 489 onto a pin 490 in the right hand leg 483. 115

Any approved means of melting and keeping the type metal in a molten state may be used, such as the 120 form shown in Fig. 19, supplied by gas from tube 491.

In order to keep the metal in the nipple, at all times, close up to its discharging orifice (to secure uniformly solid type) I divide the casting pot into two compartments—a delivery compartment 492 from which the 125 metal is forced by the pump into the mold and a supply or reservoir compartment 493 which serves as a supply or feeder reservoir. A partition 494 between the two compartments, has an overflow channel or passage way 495 substantially in line with the nipple orifice. 130

Metal is fed to the delivery compartment by means of a pump 496 operated by pump lever 469—metal entering chamber 497 through passage way 498, thence through the bottom of the hollow pump plunger 496, 5 the opening into which is controlled by a valve 499 and is discharged through outlet 500 into the delivery compartment 492, any surplus running back through the over-flow channel 495.

The pump is operated periodically by means of the 10 lever 489 fulcrumed to the back of the column and having a roll 501 in path of a cam 502 on the power shaft.

When a galley pin on the controller is called into action, the matrix case is not moved from its central position. In order to prevent the pump from working during this one revolution of the shaft, I provide a locking device as follows: In the hanger 193 already pointed out, I mount a shaft 503 having a descending arm 504 which, when moved slightly rearward, will 20 intercept the pump cam lever 489. At the other end of shaft 503 there is a horizontal arm 505 adapted to be struck by a pin 506 in the set-size index bar 186. Normally, this pin does not raise far enough to strike the arm but when the set-size index is in its central position there is no set-size pin to intercept the movement of bar and it will take an extreme upward movement, thereby locking the pump cam lever and preventing the pump's action. This device also serves as a safety device to prevent action of the pump whenever 30 the set-way index is out of position, so that the bar passes between pins of the index—as might be the case in starting up the machine.

Type assembly mechanism. As a type is cast, on each revolution of the power shaft, the cover slide of the 35 mold is withdrawn and it is ejected by the body piece against the action of the spring seated arm 56, as already described. As the mold closes to cast the next succeeding type, the type just cast is carried to the left, being held by the spring seated nick guide 50, against the end 40 of the cover slide, and landed in line with the type assembly channel 57 formed between left and right side pieces 512 and 588. It is driven into this channel or run-way by a vibrating packer 507 attached to slide 508 and operated by connecting rod 509 from a crank pin 45 510 in the upper cam and crank disk 28—the slide being mounted on a cap piece 511 suspended above left way pieces 512. The type are packed in line against a preceding or supporting block 513 attached to a slide 514 mounted in the way piece 512. This slide tends to 50 move rearward, by a cord 515, attached to a spring-actuated sheave 516. (Spring not shown.) It is prevented from so moving, during the assembly of a line, by a friction spring seated lever 517, the rear end of which bears against said slide.

55 When a line of type has been assembled in the run-way, the galley mechanism is called into action. A pair of line-carrying pawls 518, fastened so as to move together on a short shaft 519 in the end of a slide 520, are moved forward and enter the type run-way, carrying 60 the completed line forward to a position in front of a galley 521. The line slide 520 is mounted in the way 512 and held by a keeper plate 522, through a slot 523 in which, connection is made to a link 524 attached to upper end of a long elbow lever 525 fulcrumed at 526 65 to the left side of the column, and having a connecting

rod 527 by means of which movement is imparted to the slide 520, from a crank pin 528 in an outer cam and crank disk 529 on the galley shaft. This movement is followed by the raising of a "composing rule" 530 attached by arms 531 to a yoke piece 532, sliding 70 in the way 512 and having a downward projecting stem 533 held by a keeper 534 on the left side of the key box. Movement is imparted by means of an elbow lever 535 fulcrumed also at 526, acting against a pin 536 in the stem and having a roll 537 in contact with a cam 538 on 75 the galley shaft. The line is next ejected into a galley by a pair of ejecting blades 539 attached to a bar 540, whose movement is controlled by a pair of arms 541 on a rock shaft 542 mounted on left side of the way 512 and connected by an arm 543, rod 544, lever 545 and roll 546, 80 to a cam cut on the edge of crank disk 529 on the galley shaft. As the line is deposited in the galley, a pin 589 in bar 540 strikes forward end of lever 517 releasing the preceder and permitting it to return to the rear.

When the controller reaches a line or galley pin, the 85 shaft 176 is rocked, as already explained. This shaft has on its extreme left end, an arm 547 connected by link 548 to a latch arm 549, which is pivoted by a pin 550 to the upper arm of a lever 551—the pin 550 extending beyond the latch so as to engage the forward branch of a lever 552 which has a common pivot 553 with the lever 551. As the shaft 176 is rocked the latch 549 is raised from its retaining stop 554. A spring 555 tends to draw the arm forward to withdraw a stop wedge 556 on lever 552 from its engagement with the clutch pawl 95 90 14. If this movement were allowed to take place immediately the controller reaches a galley pin, the galley shaft would be started too soon and would draw out and deposit the line before the last type had been put into it. This is prevented by holding back the tripping mechanism so that it does not take effect at once, in the following manner: The lower arm of lever 551 has a pin 557 adapted to strike against a cam disk 558. This pin stands normally, when the galley shaft is out of gear, slightly away from the disk. It is put in this position 100 by a cam 559 on galley shaft, forcing backward rear arm of lever 552 to set the latch. When the latch is released it moves slightly until the pin 557 strikes its disk. The shaft 176 is returned at once to normal position, a slot in connecting link 548 permitting it to do so. On a further 105 revolution of shaft 3, the pin 557 reaches a notch 560 in its disk, thereby permitting the spring 555 to act to release the clutch pawl and start the galley shaft. This delays the line movement until the last type of the line has reached the type assembly channel. 110 115

Space-shortening devices. The spaces being cast in the same mold as the type, are full shouldered high. Such spaces are objectionable. They make correcting proof difficult and in printing direct from the type they often work up and take ink from the rollers and impress themselves on the printed page. I overcome these difficulties by cutting down the spaces to the length of the ordinary low spaces and quads of foundry manufacture. This I do in the following manner: As the type and spaces are carried to the left by the cover slide of the 120 mold, they stand in front of the packer bar directly under a knocker 561, on the front end of a lever 562, to which a vibrating motion is given by a roll 563 from a cam 564 cut in edge of crank disk 28 on the top of shaft 7. Immediately under this lever is a second lever 565 130

attached to the same fulcrum block 566 as the upper lever. This lever consists of thin spring metal. It stands normally directly under the knocker, and in this position it would be carried down by it and returned 5 with it by reason of its rear end coming in contact with the vibrator 562. The spring lever is located at a height just sufficient to clear a space and directly in the path of the heads of the type. As a type is carried to the left, its head will strike against the lever and spring it from 10 under the knocker and the type will enter the assembly way with its lower nick on a nick guide 567 of the assembly way. A space, however, will not strike the spring lever and the knocker will drive it down, causing the space to enter the assembly way with its upper nick 15 on the nick guide. This leaves the spaces hanging below the line of type as they are assembled. In like manner, an imperfect, headless type would be driven down by the knocker.

Just below the type assembly channel I mount a 20 saw 568 on a vertical axis in a hanger 569, driven by a spiral gear 570 from a gear 571 on the forward end of a shaft 572 mounted in left hand type-way 512. At the rear end a pair of spiral gears 573 and 574—the latter on vertical power shaft 7—impart motion to the 25 shaft, which is transmitted to the saw and keeps it constantly in motion when the machine is running. As the type are carried down the line by the packer or line pawls, the projecting ends of the spaces are cut off. The type runway is open at the bottom until the type 30 are past the saw, where they leave the nick guide and are carried on the bottom of the channel. Fig. 25 shows a line of type that is being assembled. Two spaces have been cut off; one is on the saw being cut and one has just entered the channel.

35 *Clogged matrix alarm.* When a matrix gets stopped up the type cast from it are short, like the spaces, and will be driven down by the knocker 561 the same as the spaces are. These spaces come at predetermined intervals, marked in the controller, while a clogged 40 matrix is liable to occur at any point. By arranging an electric alarm and closing the circuit to it at one point every time the lever 565 operates to drive down a space or short imperfect type, and opening it at another point from the controller at another point, every 45 time that a space is called for, the alarm bell will ring when a short type is driven down; but will not ring when a space is driven down. I do this by a connecting link 575 from the lever to a switch 576, adapted, when the lever is operated, to strike a contact 577 and 50 close the circuit in the wires 578. At the same time, if a space is called for, one of the special circuit breaking pins of the controller, which is set every time a space-key is struck in the key-board acts against an elbow lever 579, to open the circuit in wires 578 between two contact pieces 580, thereby preventing current from a battery 581 energizing a bell 408 to ring an alarm. If a space has not been called for by the controller—that is, if a short type has closed the circuit by switch 576, it will not be opened between points 580 55 and the bell will ring. The circuit breaking lever 519 is placed a little beyond the point where the slides take their reading to transfer settings to the matrix-placing mechanism, as a little time must elapse after a space is indicated on the controller, in which to select

its matrix, cast it, and carry it to the point where it is 65 driven down.

Leader. The type are assembled in the galley 521, the lines being packed against furniture piece 582, and are guided by side stick 583. Under the galley is a leading device mounted on a bracket 584, the leads 70 585, being carried to the left by a slide 586, actuated in any convenient manner. The left hand lead is in position to be driven upward through a suitable slot or opening by a blade 587. This being an old device and not essential to the working of the rest of the machine 75 full illustration and further description will be unnecessary.

What I claim is:

1. In a type-casting and composing machine, the combination with a matrix-case, mold and casting mechanism, 80 of means for indicating when an imperfect type is cast.

2. In a typographic machine, a matrix-case comprising parallel matrix-bars, each bar containing a plurality of matrices, means for holding the bars to move as a unit, means for moving said case in one direction to select one 85 of the bars and in another direction to select a matrix on that bar, and an alining slot adapted to receive a bar and alone the type therein.

3. In a typographic machine, the combination of the following elements, to-wit: a matrix-case comprising parallel matrix-bars, each bar having a plurality of matrices, means for moving the case in one direction to select a bar and in another direction to select a matrix; an alining slot capable of receiving a bar; and means for moving the selected bar in a third direction to seat the selected matrix 90 in said slot.

4. In a typographic machine, the combination of the following elements, to-wit: a matrix-case comprising parallel matrix-bars, arranged in the form of a sector of a regular right prism; means for rotating the case on the 100 axis of the prism to select a bar; means for moving the case parallel with the axis of the prism to select a matrix; a long alining slot, capable of receiving a bar; and means for moving the selected bar radially to seat the selected matrix in said slot.

5. In a type-casting and composing machine, the matrix 105 bar 58, having a plurality of inserted-matrices 60 all in common alinement, the ears 67 and a series of wedge-shaped notches 82.

6. In a type-casting and composing machine, a matrix-case comprising a four-sided frame and a series of parallel matrix-bars loosely connected to opposite ends of said frame.

7. In a type-casting and composing machine, a matrix 115 case comprising a frame having two curved and two straight sides, a series of pins in the curved sides, and a series of parallel matrix-bars mounted for radial movement on said pins.

8. In a machine of the class described, a matrix-case carriage, comprising two parallel bars, two cross or tie 120 bars, a matrix case mounted thereon, movable in one direction bodily with the carriage and having a movement on the carriage, the matrix-bars of the case being supported at either end by the cross bars of the carriage.

9. In a type-casting and composing machine, a matrix-case carriage, comprising two parallel bars and two connecting or tie bars, a matrix-case mounted thereon, composed of parallel matrix-bars and a connecting frame— 125 the case being movable bodily in one direction with the carriage and having a movement on the carriage, the bars 130 of the case being supported by the cross ties of the carriage, said cross ties being cut away at one point to permit the selected matrix bar to be seated on the mold.

10. In a type-casting and composing machine, a matrix-case carriage comprising two parallel bars and two connecting bars the connecting bars adapted to support the parallel matrix-bars of the matrix case and being cut away at one point to permit the seating of a matrix-bar 135 on the mold and having a pair of hooked pieces mounted thereon to support the matrix bars as they pass over the 140

- ent away portions during the selecting of a matrix, said hooked pieces being movable with the matrix case carriage, but having a movement independent of the carriage, controlled by the impression bar, which causes them to recede 5 to permit the seating of a matrix bar on the mold and which serve as stripping hooks to withdraw the matrix bar after a type has been cast, substantially as described.
11. In a machine of the class described, the combination with a mold having a fixed alining slot, of a matrix bar 10 having ears, an impression bar carrying a plunger for seating the matrix bar in the alining slot, and a pair of hooked pieces adapted to engage the ears of the matrix bar to pull it straight away from the mold after a type is cast.
12. In a machine of the class described, the combination 15 with a mold, having a fixed alining slot adapted to receive a matrix-bar, of a matrix-case having matrix-bars each with a plurality of matrices, means for selecting a bar, means for positioning a bar endwise and means for impressing the bar into the alining slot to aline the selected 20 character.
13. In a type-casting and composing machine, the combination with a mold having a fixed alining slot, of a matrix-case having matrix bars, means for selecting a matrix-bar, an impression device for seating and positioning the selected bar, a pair of withdrawing or stripping hooks and means for moving said hooks simultaneously to withdraw the matrix bar from the mold after a type has 25 been cast.
14. In a type-casting and composing machine, the combination with a matrix bar having ears at its ends, of an impression plunger for impressing the matrix-bar against a mold, a pair of hooks engaging the ears of the matrix bar when the bar is at the impression point, which hooks are adapted to recede slightly ahead of the impression 30 plunger as the matrix bar is seated and to withdraw the matrix bar straight away from the cast type on the return or back-stroke of the impression plunger.
15. In a type-casting and composing machine, the combination with a mold having a fixed alining slot, of a matrix-bar having a plurality of matrices in common alinement and a corresponding series of positioning notches, and an impression plunger adapted to force the matrix bar into the alining slot to position and seat the selected 40 matrix on the mold, substantially as described.
- 45 16. In a type-casting and composing machine, an impression or matrix seating device comprising an impression bar, a rock shaft, arms and connecting links to said impression bar, an impression and positioning plunger mounted on said bar and a pair of matrix stripping and supporting hooks having a movement on the impression bar which is controlled by the matrix case carriage and movable with the bar to and from the mold, substantially as described.
- 50 17. In a type-casting and composing machine, a type mold having a pair of alining plates, said plates being attached at one end to the cheek pieces of the mold and at the other end to an upwardly extending portion of the mold base, in combination with a matrix bar and means for impressing said bar onto the mold between the alining plates.
- 55 18. In a machine of the class described, the combination with a matrix-case of a set-size index, said index having as many independent setting surfaces as there are matrices in the case.
- 60 65 19. In a type-casting and composing machine, the combination with a matrix-case and a mold having an adjustable body piece, of a set-size index, movable in two directions simultaneously with the matrix-case, and connections between the index and the body piece to vary the position of the latter.
- 70 75 20. In a type-casting and composing machine, the combination with a mold having an adjustable body piece, of a matrix-case, a set-size index having an independent setting surface for each matrix in the case, and connections from the index to limit the mold body piece to correspond with the set of the letter whose matrix is at the casting point.
21. In a type-casting and composing machine, the combination with a matrix-case and a mold having an adjustable body piece, of a set-size index having a separate and 80 distinct setting surface for each matrix of the case, said index being movable in two directions simultaneously with the case, and connections from the index to vary the setting of the body piece.
22. In a type-casting and composing machine, a matrix case, a mold body piece, a set-size index having contact surfaces arranged in rows in two directions corresponding to the rows in the matrix case, means for moving the same in two directions simultaneously with the matrix case, a reading bar or finger adapted to be thrust yieldingly against the index and connections from the bar to limit the setting of the body piece, substantially as described. 85
23. In a type-casting and composing machine, the combination of the following elements, to wit: a mold body piece; a stepped limiting stop therefor; a spring or equivalent fending to hold the stop so as to limit the body piece to its smallest allowable movement; a set-size index; a reading finger co-acting therewith and connections from the same to withdraw the body piece limiting stop, substantially as described. 90
24. In a type-casting and composing machine the combination with a mold having an adjustable body piece, of a matrix-case, a set-size index having contact surfaces corresponding to the matrices of the case, means for selecting a matrix, means for selecting a contact surface of the index, and means controlled by the contact surface for positioning the body piece for the proper "set" of the matrix selected. 100
25. In a type-casting and composing machine, the combination with a mold having an adjustable body piece, of a matrix-case, a set-size index having contact surfaces corresponding to the matrices of the case, a bar or reading member adapted to take a reading from the contact surfaces, means for selecting a matrix, means controlled from the matrix selecting devices for relatively positioning the index and reading member and connections from the reading member to transfer its settings from the index to the mold body piece. 110
26. In a type-casting and composing machine, the combination with a mold having an adjustable body piece, of a matrix case having matrices disposed in a by-factored arrangement, a set-size index having contact surfaces corresponding to the matrices of the case, a reading member adapted to take a reading from the index, means for selecting a matrix, means for simultaneously selecting a contact surface, and connections, from the reading member to transfer its settings from the index to the mold body piece. 120
27. In a type-casting and composing machine, the combination with a mold having an adjustable body piece, of a matrix case, movable in two directions to select a matrix, a set-size index having contact surfaces corresponding to the matrices of the case, a bar or reading member, means for selecting a matrix, means for simultaneously moving the index, means for thrusting the bar or reading member yieldingly against the index, and connections from the same to limit the mold body piece. 130
28. In a type-casting and composing machine the combination with a mold having an adjustable body piece of a matrix-case comprising bars each with a plurality of matrices, connections from a matrix selecting mechanism to rock the case to select a bar and to move it bodily to select a matrix, a set-size index mounted on the connections from the matrix selecting mechanism so as to move simultaneously with the matrix case, said index having pins or contact surfaces, a reading member, means for thrusting the same yieldingly against the index and connections therefrom to vary the settings of the mold body piece, substantially as described. 135
29. In a machine of the class described the combination of the following elements, to wit: a matrix-case carriage; a shaft having gears in mesh with racks of said carriage and adapted to move the same back and forth; a matrix-case mounted on the carriage; a shaft having its axis parallel to the direction of movement of the carriage; connections from the shaft to move the matrix case on the carriage when said shaft is rocked; a sector gear on the last mentioned shaft; a rack in mesh with the sector; connections to said rack and the first mentioned shaft, from the matrix placing mechanism, substantially as described. 140
30. In a typographic machine, the combination with a matrix-case having parallel matrix bars, of a matrix-case 145
- 150
- 155
- 160

- carriage having cross bars adapted to support the matrix-bars, said cross bars being cut away to permit the setting of the matrix bar on a mold, and means for temporarily filling said cut-away portions of the cross bars during the 5 rearrangement of the case to select a matrix.
31. In a machine of the class described, the combination of the following elements, to wit: a matrix-case mounted to move in two directions; a matrix-placing mechanism; two connections from the matrix placing mechanism—one 10 for each movement of the matrix case—a set-size index mounted to move in two directions, its movements being controlled by the movements of the connections above mentioned.
32. In a machine of the class described, the combination 15 of the following elements to wit: a matrix-case mounted for movement in two directions; a matrix placing mechanism; two intermediate connections, consisting of a rock shaft and a rack; a set-size index mounted on the rock shaft to turn with it and having a movement on the rock 20 shaft controlled by the movement of the rack, substantially as described.
33. In a type-casting and composing machine, the combination with a mold and a casting mechanism adapted to cast type and shoulder-high spaces, or a type assembling 25 mechanism and a space shortening device.
34. In a type-casting and composing machine, the combination with a mold and casting mechanism of means for casting type and word spaces, means for assembling the same in a galley, a space shortening device located between 30 the casting mechanism and the galley and means for causing the space shortening device to act on the word spaces in their passage from the mold to the galley.
35. In a type-casting and composing machine adapted to cast type and shoulder-high spaces, a cutter adapted to 35 cut in two the spaces and quads and means between the casting and assembly points for bringing the spaces and quads against the cutter.
36. In a machine of the class described, the combinations with a type channel or runway, of means for assembling and moving a line of type and spaces therein, a cutter located in proximity to the runway, and means for projecting the spaces so as to come in the path of the cutter, for the purpose set forth.
37. In a machine of the class described, the combination 40 with a type channel or runway having one nick guide, of type having two nicks, means for shifting certain of the type from one nick to the other, a cutter in proximity to the type runway adapted to cut off the end of the shifted type.
38. In a type-casting and composing machine, the combination of the following elements to wit: a type mold having two nick pieces; a nick guide carried by the cover slide; means for alighting said nick guide with one of the nick pieces, when the cover slide is withdrawn to allow 45 the body piece to discharge the type; a type runway having one nick guide adapted to line with the lower nick of a type in its normal movement from the casting point; means for shifting the type spaces before they enter the line of assembly so that the upper nick will enter on the nick guide of the type way, substantially as described.
39. In a type-casting and composing machine, the combination with a mold and casting mechanism for casting type and word spaces, of a type assembly channel or runway, means for assembling the type in normal position, 50 means for assembling the word spaces in an abnormal position—one end projecting below the line—means for shortening or cutting off the projecting word spaces.
40. In a type-casting and composing machine, the combination with a mold and casting mechanism for casting type and word spaces, of a type assembly channel or runway, means for causing the knocker to act on the spaces to drive them down, whereby the spaces will stand below the line of type.
41. In a type-casting and composing machine, the combination with a knocker placed in proximity to the type 55 way of means for causing said knocker to act on the spaces and headless type to project them below or beyond the normal line of type.
42. In a type-casting and composing machine, a vibrating knocker adapted to drive down type and type spaces
- in combination with a throw-off device placed in the path of the head of the type, whereby a normal type throws off the knocker and a space or headless type permits the knocker to act, substantially as described.
43. In a type-casting and composing machine, the combination of the following elements, to wit: a mold and casting mechanism; a type assembly runway; a revolving cutter or saw just below the path of the line of type; a knocker placed at the entrance of the type-assembly runway; means for causing the knocker to drive down the spaces and quads into the path of the saw and means for moving the line of type in the runway past the saw to shorten the spaces, substantially as described.
44. In a type casting and composing machine, an alarm device for imperfect type comprising an alarm, means normally causing said alarm to act whenever a space or headless type is cast, means for neutralizing the action of the alarm and rendering it inoperative when a space is cast, but allowing it to operate when a headless type is cast.
45. In a type casting and composing machine, an alarm device for imperfect or headless type, said alarm being normally adapted to operate on the casting of spaces and headless type, in combination with connections from the controller to neutralize the action of the alarm and render the same inoperative on the casting of indicated spaces and quads.
46. In a type-casting and composing machine, the combinations with a vibrating knocker adapted to drive down spaces and headless type of a circuit closing device, means for operating said device to close an electric circuit whenever a space or headless type is driven down, an alarm device in the circuit and a circuit breaker, means actuated from the controller to operate the circuit breaker simultaneously with the circuit closing device to prevent the alarm acting when a space is driven down.
47. In a type-casting and composing machine, an alarm device normally tending to operate whenever a space is cast in combination with means actuated by a controller to neutralize the alarm and render it inoperative when the space cast was indicated on or called for by the controller.
48. In a type-casting and composing machine, the combination with a type mold having the usual cheek pieces, nick pieces, body piece and cover slide, of a movable nick guide mounted in said cover slide, means for alining the said guide with one of the nick pieces of the mold and withdrawing the cover slide so that the type has free egress when ejected by the mold body piece, means for supporting the type and holding it against the end of the body piece as it is ejected from the mold, and means for causing the nick guide of the cover slide to clamp the type against said cover slide.
49. In a type-casting and composing machine, the type sustaining arm 56 adapted to support the type and spaces against the action of a mold body piece in ejecting them from the mold.
50. In a type-casting and composing machine—a mold comprising the usual cheek piece, body piece, and cover slide; said cover slide having a swinging nick guide 50 pivoted therein and means for rendering said guide spring seated.
51. In a place-finder for typographic machines the combination with finger keys, of a plurality of corresponding indicating pieces therefor, connections from the finger keys to set the indicating pieces in succession and means for identifying the indicating pieces.
52. In a place-finder for typographic machines, the combination with finger keys, of a corresponding plurality of indicating pieces, connections from the finger keys to set the indicating pieces in succession, an identifying index having the characters of the key-board marked thereon, mounted so as to be adapted for use in reading the settings of the indicating pieces.
53. In a place-finder for typographic machines, the combination with a finger key-board, of a plurality or set of indicating pieces for each finger key, the corresponding 155 pieces of the several sets being arranged in common rows, connections from the finger keys to set pieces in successive rows, and an identifying index adapted for use in reading the settings of the indicating pieces.
54. In a place-finder for typographic machines the com-

- bination with finger keys of a corresponding series of indicating pieces, means for setting one of said pieces at every stroke of a finger key and means for feeding said indicating pieces bodily at each stroke of said key.
5. 55. In a place-finder for typographic machines the combination with finger keys of corresponding series of indicating pieces, the pieces of the different series being arranged in common rows, means for setting one of said pieces at every stroke of a finger key and means for feeding said indicating pieces, bodily one step with each stroke of said key.
6. 56. In a place-finder for typographic machines the combination with finger keys of corresponding series of indicating pieces, arranged in transverse rows, corresponding in numbers to the number of characters that may be indicated, means for setting one piece in each succeeding transverse row at every stroke of a key, and an identifying index having characters corresponding to the finger keys arranged in proximity to the indicating pieces.
10. 57. A place-finder for typographic machines, comprising series of indicating pieces corresponding to the finger keys, and an identifying index having the characters of the key-board arranged in proximity to their corresponding series of indicating pieces, connections from each key lever to set one of the indicating pieces and bring it to correspond with the same character marked on the scale.
20. 58. A place-finder for typographic machines comprising a cylinder or tube having movable pieces or pins arranged in rows in two directions—circular rows corresponding to the finger keys and axial rows corresponding to the number of characters to be indicated—means for setting one of said pins and means for revolving said cylinder one step at each stroke of a key.
30. 59. A place-finder for typographic machines comprising a tube or cylinder having radial pins arranged in rows in two directions, said pins standing normally in an outward position; connections from the key levers to drive down their corresponding indicating pins, an identifying index and means for feeding said cylinder so that the pin just driven comes under a corresponding character marked on said index.
35. 60. In a place-finder for typographic machines, rows of indicating pieces each piece in the row corresponding to a character on the key-board, means for setting one piece in each succeeding row as the keys are struck and an identifying index having characters of the key-board marked thereon and adapted to be moved over a limited number of rows to facilitate the reading of the pieces which have been set.
40. 61. A place-finder for typographic machines comprising a tube or cylinder having rows of pins and an identifying index as described and shown, means for setting pins corresponding to the keys struck in the key-board, means for feeding or revolving the cylinder with each stroke of a key, and means for restoring the pins to normal position before they again reach the setting point.
45. 62. In a place-finder for typographic machines, the combinations of the following elements, to wit: A tube or cylinder, having rows of pins; an identifying index; means for setting the pins and revolving the cylinder; means for returning the pins before they again reach the setting point and means for throwing off the pin returning device, for the purpose set forth, substantially as described.
50. 63. In a machine of the class described a die or matrix placing mechanism comprising a series of movable pieces, means for moving the outside members in opposite directions to secure the full or greatest throw of the matrix case and means for connecting the actuated pieces with their next adjacent piece to move in the same direction, but one step less, means for connecting the parts which control the positions of the matrix case to any member of the series.
55. 64. In a machine of the class described a matrix placing mechanism comprising a series of parallel slides, means for moving the outside slides in opposite directions, means for causing each outside slide to draw the next adjacent slide in the same direction one step less and so on to the two central slides and means for limiting the movement of these when they have each moved one step in opposite directions, means for connecting the parts which carry the matrix case to any slide so as to secure movement of the matrix case in any desired direction, substantially as described.
65. 65. In a machine of the class described a die or matrix placing mechanism comprising a series of parallel slides means for giving a portion of the slides a movement in one direction varying by steps and means for giving the other portion a movement in the opposite direction varying by steps, means for making connections from the slides to secure the movement of the die case in any desired direction.
70. 66. In a machine of the class described the combination with a matrix case and a matrix placing mechanism having a series of parallel slides of means for locating or placing the slides in a uniformly stepped position and means for making connections to the slides to secure any desired movement of the die case.
75. 67. In a machine of the class described a die or matrix placing mechanism comprising a series of parallel slides means for moving the slides to stepped positions in opposite directions, as described and shown, one set of connections from the slides adapted to locate the matrix case to select a row of matrices and a second set of connections adapted to locate the case to secure the selection of any desired matrix, the case being movable in any direction from central or normal position.
80. 68. In a machine of the class described the combination with a matrix placing mechanism consisting of parallel slides movable to stepped positions in opposite directions, as described and shown, of a pair of frames adjacent to said slides each carrying a series of connecting pins adapted to be projected into recesses in the slides when in their normal or home position, connections from one frame to rock the matrix case to secure the selection of a matrix bar and connections from the other frame to move the matrix case carriage, and means for projecting pins from the frames into the slides and means for moving the slides to secure the selection of the desired matrix.
85. 69. In a machine of the class described, the combination with a die or matrix placing mechanism comprising a series of slides having a stepped movement in opposite directions, of a pair of frames carrying connecting pins, means operated by a controller for projecting pins from the frames into the slides and connections from the frames to the die case, substantially as described.
90. 70. In a machine of the class described the combination with a die or matrix placing mechanism comprising a series of parts movable to stepped positions in opposite directions, of a matrix case movable in two directions to select a matrix, connections from the case to the matrix placing mechanism and means for joining or connecting the same to one or more of the variably moving parts of the placing mechanism, to secure the necessary movements of the matrix-case.
95. 71. In a machine of the class described the combination with a matrix placing mechanism comprising a series of parts movable to stepped positions in opposite directions, of a matrix case, connections from the case to the placing mechanism, a controller, connections from the controller adapted to control the connections to the matrix placing mechanism to secure varying movements from the same to locate the die case in the position desired as indicated by the controller.
100. 72. In a machine of the class described, the combination with a matrix placing mechanism comprising a series of slides having stepped movements, as shown, of a pair of frames having connecting pins, means for projecting the pins into the slides, means for moving the slides, to carry the frames to secure the selection of a desired matrix, means for returning the slides and frames to normal position, a series of pins in the placer slides and means for moving the same to return the connecting pins to their normal position.
105. 73. In a machine of the class described, a matrix placing mechanism, comprising a series of parts, means for moving one part positively, means for connecting the adjacent parts to secure uniformly stepped movements.
110. 74. In a typographic machine, a matrix placing mechanism comprising a series of slides, each slide being con-

- nnected to the next adjacent slide, by a pin in one entering a slot in the other.
75. In a machine of the class described, the combination with a controller having actuating pins, of a mechanism adapted to take a reading therefrom and transfer the same to a matrix-placing mechanism, comprising a vertically movable carrier or frame having slides, means for lowering the frames so the slides are moved by actuating pins of the controller to engage vertical slides, means for moving the frame to raise the vertical slides, cam surfaces or wedges on the vertical slides adapted through intermediate pins to drive the connecting pins into the matrix-placing slides, means for returning the vertical slides on the downward movement of the carrier and a positive or cam movement for returning the slides.
76. In a device for transferring the settings of a controller to a die-placing mechanism, a vibrating frame having slides set by pins of the controller, means for vibrating said frame—the connection to the frame being a yielding one, in combination with means for locking the frame against upward movement whenever two slides of the same set have been called into action and means for operating an alarm in connection therewith.
77. In a typographic machine, the combination with a controller having actuating pins, of a matrix-placing mechanism, means for transferring the reading of the controller to the matrix-placing mechanism, comprising the slides 151 carried by vibrating frame 152, a safety device for indicating when an improper number of actuating pins have been set, said safety device consisting of cords 165, pins 167, and pawl 166, cooperating with a notch in the slide 168 to stop the movement of the vibrating frame.
78. In a controller for typographic machines, the combination with bars or tubes carrying actuating pins, of means for linking the bars together and means for keeping the bars from turning.
79. A controller for typographic machines comprising bars or tubes having actuating pins, said bars being fastened together in pairs and the pairs joined together by links at either end.
80. In a controller for typographic machines, the combination with bars carrying friction-held actuating pins, of means for fastening the bars together in pairs—whereby the actuating pins will present constant striking surfaces when called into action—and means for linking the bars together at either end into an endless belt or chain.
81. In a machine of the class described, an endless controller composed of bars or tubes carrying actuating pins, said bars being fastened together in pairs, the bars being connected at their ends by links held by pins which project from the end of the bars and which serve the double purpose of pivoting the parts together and supporting the controller on its feed sprockets, substantially as described.
82. In a machine of the class described, an endless controller composed of hollow bars or tubes, each tube carrying a series of friction-held actuating pins, means for keeping the bars from turning so that the actuating pins will always be in the same position when passing the setting, controlling and returning points.
83. A controller for typographic machines composed of hollow bars or tubes fastened together in pairs each bar carrying actuating pins mounted in the tubes in such a direction that the pins of each pair would, if produced or extended, meet at a common point.
84. A controller for typographic machines comprising tubes connected in pairs, pins projecting from the end of said tubes, by means of which the controller is supported and fed over a pair of sprocket wheels, each bar containing a series of actuating pins, mounted so as to have a radial movement, when the controller is passing over the sprocket wheels—the bars being joined together into an endless chain or belt by links, substantially as described.
85. In a controller, the combination with a hollow bar having a series of actuating pins mounted therein, of a friction therefor comprising a coiled or helical spring, substantially as described.
86. In a controller for typographic machines, the combination of the bars 131; the end pins, 135; links, 134; and the pins, 136—the latter passing through a pair of bars and pins 135, for the purpose set forth.
87. In a typographic machine, the combination with a controller having a series of movable actuating pieces, of a series of plungers adapted to set said actuating pieces a key mechanism, and means for moving the plungers by inertia derived from the key stroke.
88. In a key mechanism for typographic machines, the combination with the key levers, of corresponding hammer pieces adapted to be moved positively by the key levers a certain distance, and having an additional movement due to momentum or inertia, a series of rock shafts, adapted to be moved by the hammer pieces in making their additional movements and connections from the rock shafts to secure the selection of characters.
89. In a machine of the class described, the combination with the key levers, of corresponding hammer pieces adapted to be moved positively by the key levers a certain distance and having an additional movement due to momentum or inertia, a controller having actuating pieces, and connections to the hammer pieces whereby their excessive movement sets the actuating pieces of the controller.
90. In mechanism for setting actuating pieces of a controller, the combination with key levers 214, of hammer pieces, 216; rock shafts, 210 and plungers 206, substantially as described.
91. In a machine of the class described, the combination with a controller having movable actuating pieces, of means for setting the same by an additional or excessive movement of a hammer piece due to inertia derived from a key stroke, means for returning the setting parts positively the distance moved by the additional momentum stroke.
92. In a machine of the class described, the combination with a controller having movable actuating pins, of a key mechanism adapted to set said pins by a momentum stroke, a power driven shaft and means for revolving the same at each stroke of a key to return the pin-setting parts the amount of their excessive or setting movements and to feed the controller.
93. In a key mechanism adapted to set pins of a controller and to release an escape shaft, the means substantially as described for positively releasing the escape shaft and the means substantially as described and shown, for setting the pins of the controller by virtue of an excessive movement of a hammer piece due to its momentum or inertia.
94. In a key mechanism, the combination with finger key levers of hammer pieces adapted to be moved by the key levers a certain distance and to move an additional distance by virtue of inertia imparted to them, of a power driven shaft and connections therefrom to return the hammer pieces to the position to which they were moved positively by the finger keys.
95. In a machine of the class described, the combination with a controller having a series of movable actuating pieces, of a corresponding series of plungers and rock shafts, of hammer pieces adapted to impart movements by virtue of their momentum to the rock shafts and plungers, means for returning the plungers and rock shafts to the position to which they were driven positively by the finger keys.
96. In a machine of the class described, the combination with an endless controller, of a die- or matrix-placing mechanism, and an intermediate mechanism adapted to read the controller and transfer said reading to the die-placing mechanism.
97. The combination with an endless controller, of a finger key mechanism for setting the actuating parts of said controller, intermediate mechanism for reading the controller and transferring said reading to the die or matrix-placing mechanism, means for feeding the controller to the matrix-placing mechanism, means for stopping the movement of the controller when it has caught up with the setting mechanism, means for starting the controller, when slack is given it by the setting mechanism, substantially as described.
98. In a type-casting and composing machine, the combination with a casting device, of a matrix-placing mechanism, a controller therefor comprising an endless belt or chain with bars having actuating pins, a key mechanism and connections therefrom to set the actuating pins, means

- for feeding the controller direct from the setting mechanism to the controlling mechanism of the casting device, and means for automatically stopping and starting the movement of the controller to the matrix-placing mechanism. 10. In a type-casting and composing machine the combination with a set-size index having connections to transfer readings to limit the mold body piece to cast characters and spaces of proper size, of a controller and a line word-space regulator, means operated by the controller, for taking a setting from the line word-space regulator instead of the index, when justifying spaces are to be cast. 85
110. A justifier for typographic machines comprising a plurality of adjacent parallel parts, having the relative longitudinal movement of an arithmetical progression, dependent on the number of word spaces in a line, in combination with a line word-space regulator—the justifier and regulator having relative longitudinal movement dependent on the amount of letter and normal word space registered and means for transferring the setting of the justifier to the line word-space regulator. 111. In a type-casting and composing machine the combination with a mold and casting mechanism of a matrix case under action of a controller, a normal or ordinary body piece positioning device for setting the body piece on said mold to cast type and spaces of a size corresponding to the selected matrix, a plurality of line word-space regulators and means operated by the controller for setting 90 the body piece from one of the regulators when the matrix case is in position to cast justifying spaces.
112. In a typographic machine the combination with a plurality of word-space regulators each adapted to be set to control the word spacing of a line, of means for setting 100 them and bringing them into action successively to justify lines of type, substantially as described.
113. In a typographic machine, the combination with an endless controller of a plurality of line word-space regulators, means for setting successive line sections of the 105 controller to select the characters for a line, means for setting corresponding word-space regulators, means for calling the line word-space regulators into action to justify their corresponding lines of the controller.
114. In type-casting and composing machine the combination with an endless controller of a plurality of line word-space regulators, means for setting successive line sections of the controller to select the characters for a line, means for setting corresponding line word-space regulators, a matrix selecting and casting mechanism, means 115 for feeding the controller to the same, means for circulating the word-space regulators to bring them into action to justify their corresponding lines on the controller.
115. In a typographic machine, a plurality of word-space regulators and means for circulating the same to 120 bring them into action successively to justify lines of type.
116. In a machine of the class described the combination with a plurality of line word-space regulators comprising blocks having pins arranged in rows in one direction corresponding to the greatest possible number of 125 justifying spaces that may be cast for a line and in rows in another direction corresponding to sizes of spaces, of means for setting the pins from a justifier, a mold having an adjustable body piece, a controller and means operated thereby for transferring the settings of the regulators to 130 the body piece limiting device when justifying spaces are to be cast, means for circulating the regulators to bring them successively into action, to justify lines represented by successive sections of a controller, substantially as described. 135
117. In a machine of the class described the combination with a line word-space regulator, of means for setting the same to justify a line on the quotient and remainder principle when there is an integral number of units to be added, means for transferring the settings of the regulator to the mold body piece when justifying spaces are to be cast, and means for varying the setting of the body piece for one of the spaces by reducing it a fraction of a unit from that fixed by the regulator, when there is a fraction of a unit to be eliminated. 140
118. In a type-casting and composing machine the combination with a justifier adapted to limit the mold body piece to cast justifying spaces varying from each other by whole or integral units, means for varying the connections from the justifier to cast one space a fraction of a unit less than that called for by the justifier, when there is a fraction of a unit to be eliminated. 145
119. In a typographic machine the combination with a justifier adapted to operate on the quotient and remainder principle, of means for setting the same to justify according to the quotient and integral remainder, means for varying or changing certain of the justifier settings when necessary in order to eliminate fractions of a unit of the remainder. 155
120. In a typographic machine, the combination with a justifier adapted to operate on the quotient and remainder principle, of means for setting the same to justify according 160
5. A justifier for typographic machines comprising a relatively fixed part mounted for movement in a transverse direction only, and a plurality of adjacent parallel parts mounted for movement longitudinally and transversely. 10. A justifier for typographic machines comprising a relatively fixed part, mounted for transverse movement only and a plurality of adjacent parallel parts mounted in racks 30 or slides for longitudinal movement and having a transverse movement on the racks and means controlled by the word register for positioning the parts of the justifier in a uniformly stepped position. 11. A justifier for typographic machines comprising a relatively fixed part mounted for transverse movement only and a plurality of adjacent parallel parts mounted in racks or slides for longitudinal movement and having a transverse movement on the racks, a set of varying gears in mesh with the racks, connections from the word register 40 to move one of the racks and through the gears above mentioned to move the other racks so as to locate the parts of the justifier in uniformly spaced or stepped positions, substantially as described. 12. A justifier for typographic machines comprising a plurality of parts, means for positioning the same from the word space register, a line word-space regulator, and means for positioning the same from the unit register and a striker plate for transferring the setting of the justifier to the line word-space regulator. 13. A justifier for typographic machines comprising the combination with a plurality of line word space regulators, of a justifier automatically set from the registering devices and means for transferring the settings of the justifier to the regulators. 14. A justifier for typographic machines comprising the combination with a plurality of word-space regulators having movable parts or pins capable of being set to control the spacing of a line, of means for positioning the same in proximity to the justifier and means for transferring the setting of the justifier to the regulator. 15. In a machine of the class described the combination with a plurality of line word space regulators, of a justifier automatically set from the registering devices and means for transferring the settings of the justifier to the regulators. 16. In a machine of the class described the combination with a plurality of word-space regulators having movable parts or pins capable of being set to control the spacing of a line, of means for positioning the same in proximity to the justifier and means for transferring the setting of the justifier to the regulator. 17. In a machine of the class described the combination with a plurality of word-space regulators having rows of movable pins—as many rows as there are possible justifying spaces in a line—of means for setting said pins from a justifier and means operated by the controller for bringing the settings of the regulator into active position to justify the line. 18. In a machine of the class described the combination with a plurality of line word-space regulators of means for setting the same from a justifier and means operated by the controller for bringing the settings of the regulator into active position to justify the line. 19. In a type-casting and composing machine the combination with a mold having an adjustable body piece, of a plurality of word-space regulators, having rows of pins corresponding to the greatest possible justifying spaces in a line, of means for setting said pins from a justifier, a controller and means operated thereby for bringing the settings of the regulators into active position to limit the 75 setting of the mold body piece to cast spaces to justify the line. 20. In a typographic machine, the combination with a justifier adapted to limit the mold body piece to cast spaces to justify the line.

- ing to the quotient and integral remainder, means for indicating a fractional unit in the remainder when there is any, means controlled thereby for varying the justifier settings, at certain of the word spaces when necessary to eliminate said fractional units. 85
121. In a type-casting and composing machine the combination with mechanism for limiting the positions of the mold body piece of connections therefrom to set-size regulating devices, means for varying the setting of the body piece independent of the set-size regulating devices, to change the mold operating a fractional unit. 90
122. In a type-casting and composing machine a mechanism for limiting the positions of the mold body piece, comprising a stepped stop piece, size-setting devices, a connection from the stepped stop piece to said size-setting devices, independent means for varying the position of the stepped stop piece to cast a type or space a fraction of a unit smaller than indicated by the size setting devices. 95
123. In a type-casting and composing machine the combination with a mold body piece limiting stop, of a hooked withdrawing piece for the same, said withdrawing piece being controlled by size-setting devices, a stepped connection between the mold body piece limiting stop and the hooked withdrawing piece, whereby the position of the limiting stop may be varied independent of the size setting devices, substantially as described. 100
124. In a type-casting and composing machine the combination of the following elements, to wit: a matrix-placing mechanism, mold and casting mechanism under action of a controller; means, when the matrix case is in position to cast justifying spaces, of yieldingly thrusting a bar or feeler against one of the stops of a line space regulator, connections therefrom to limit the body piece of the mold to cast a justifying space; means for feeding the thrusting device one step each time it is called into action; and means, called into action by the first stroke of the thrusting device, to vary or change the setting of the body piece from that given it by the pin of the regulator when there is a fractional or half unit to be added. 105
- 40 125. In a mechanism for transferring the readings from a line word-space regulator to the body piece of a mold, in a type-casting and composing machine, means cooperating with a device called into action by a special fraction pin of the regulator, for varying the setting of the body piece half a unit at one particular space. 110
126. In a type-casting and composing machine the combination with mechanism for transferring the settings of a line and space regulator to the mold body piece of the electrical connections, as described and shown, cooperating with a special fraction pin of the regulator, for varying the setting of the body piece half a unit when casting the first justifying space of a line. 115
127. In a machine of the class described a line word-space regulator having actuating pieces or stops adapted to control the justification of a line with spaces varying from each other by integral units, a special pin or actuating piece, adapted to be set by the unit register when there is a fractional unit to be eliminated and which, when so set, calls into action devices for varying the setting of the mold body piece a fraction of a unit on casting the first justifying space. 120
- 55 128. In a typographic machine a registering device adapted to register whole and half units, in combination with a justifier for effecting justification on the quotient and remainder principle, connections from the register to set the justifier according to the registered integral units and connections from the register adapted to vary or reduce the size of one space by making it half a unit less than called for by the justifier, when necessary to justify the line. 125
- 60 129. In mechanism for effecting justification upon the quotient and remainder principle, for typographic machines, a register for letter space and normal word-spaces adapted to register whole and half units, means for setting the justifier in accordance with the registered integral units and means for eliminating the registered half unit, if any, by making the size of one of the spaces half a unit less than that called for by the justifier. 130
- 70 130. In a typographic machine, the combination with a justifier adapted to operate on the quotient and remainder principle, of a register for letter and normal word spaces adapted to register whole and fractional units, means for setting the justifier in accordance with the registered integral units, and means for eliminating fractional units by reducing certain of the word spaces. 135
131. In a unit registering mechanism for typographic machines a primary registering device for whole or integral units, a secondary register for half units, in combination with means for transferring the record of the latter to the former when the accumulated fractional increments become integral. 90
132. In a unit registering mechanism for typographic machines a primary registering wheel for whole or integral units, a secondary register for half units, in combination with means for transferring the record of the latter to the former as soon as two half units have been recorded and means for returning the secondary register to its zero or starting position. 95
133. In a machine of the class described the combination of the following elements, to wit: a unit register comprising a ratchet wheel; a feed pawl therefor mounted on a slide or its equivalent and normally tending to draw the pawl to take its maximum number of teeth a plurality of limiting stops, spring-seated to engage the slide and limit the pawl; a key mechanism and escape shaft; connections from the finger keys to release one of the limiting stops and to release the escape shaft; connections from the escape shaft to permit the pawl-carrying slide to move until intercepted by the stop and then to return the slide to its normal or starting position to feed the ratchet wheel; and connections to return the limiting stops to their latched position. 100
134. In a unit register for typographic machines the combination with a ratchet wheel and feed pawl therefor tending to take its maximum throw, of a latch for the feed pawl and a set of limiting stops adapted to remove the latch and limit the throw of the pawl, substantially as described. 105
135. In a typographic machine the combination of the following elements, to-wit: a unit registering ratchet wheel; a suitably mounted feed pawl therefor, tending to take its maximum throw; a key mechanism and escape shaft with connections from a finger key to release the latter; connections from the escape shaft to operate the feed pawl; a latch for the feed pawl and a plurality or series of limiting stops adapted, when released by connections from the finger keys, to raise the latch and limit the pawl. 110
136. In a typographic machine the combination with a unit register having a registering ratchet wheel and feed pawl therefor, of a series of limiting stops and means for actuating the same and a latch to prevent movement of the pawl unless a limiting stop has been set, substantially as described. 115
137. In a unit registering mechanism having a registering ratchet wheel and feed pawl therefor, the combination with a series of limiting stops adapted to limit the feed of the ratchet pawl by steps, of a backing or resistance for the limiting stops; means for removing the backing piece to permit a limiting stop yielding one step to register one more unit than the normal throw corresponding to that stop. 120
138. In a machine of the class described the combination with finger keys, of a unit register comprising a primary integral unit counting ratchet wheel, a feed pawl and set of variable limiting stops therefor representing whole or integral units, connections from the finger keys to bring the stops into active position, a backing for the limiting stops and a second or fraction registering device, controlled from the finger keys, adapted to remove the backing when the sum of the fractional increments have reached a unit to permit the limiting stops to yield to add that unit to the primary registering wheel. 125
- 75 139. In a unit register for typographic machines the combination with a ratchet wheel, of means for returning the same to zero position, a stop on the wheel near its periphery, a swinging arm cooperating with said stop to limit the wheel exactly in its zero position, a scroll to carry the swinging stop arm out of the path of the wheel stop to permit the wheel making more than one revolution. 130
- 80

- and to return the arm to position to intercept the wheel stop when the ratchet wheel has again reached its zero position.
140. In a typographic machine the combination with a unit register having a set of limiting stops normally tending to seek an active position, of shouldered latch pins therefor and connections from finger keys to release the same. 85
141. In a typographic machine the combination with a unit register having a set of limiting stops, normally tending to seek an active position, of latches for said stops and means for releasing them due to the momentum of a stroke of a finger key, substantially as described. 90
142. In a typographic machine the combination of the following elements, to-wit: a registering mechanism having a set of limiting stops, normally tending to seek an active position; latches for said stops; a series of rock shafts having arms adapted to move the latches; a series of vertical hammer pieces and a corresponding series of finger keys and levers adapted by slow movement to raise the hammer pieces and move the rock shafts into contact position with the latches and by a quick or staccato stroke to impart an excessive movement to the hammer pieces and rock shafts—due to their momentum or inertia—and 95 to thereby release the limiting stops.
143. In a machine of the class described the connections from the starting key, substantially as described and shown, for setting the justifier, releasing the escape shaft, driving a line or galley pin, feeding the controller, releasing the unit registering and word counting devices. 100
144. In a machine of the class described the combination of the following elements, to-wit: a unit registering wheel; a sector mounted on the shaft or axis of said wheel; the stop device shown and described for causing the movement of the unit register to move the sector when the register has reached a point within the range of justification; a rack in mesh with the sector having a pawl or latch adapted to enter the path of a line word-space regulator and to position the same in reference to a justifier, according to the total line and normal word space. 105
145. In a justifier for typographic machines, the combination with a plurality of line word-space regulators, of a connection from a unit registering mechanism adapted to enter the path of the regulators to locate it in reference to a justifier according to the total amount of letter and normal word space, and an escapement also adapted to enter the path of the regulators to hold back the regulators and prevent but one of them at a time coming into the setting zone of field. 110
146. In a typographing machine the combination of the following elements, to wit: connection 426 from the unit register; the circulating line word-space regulators 346; latch 427; incline or wedge 451 for withdrawing the latch as the rack 426 is released by the starting key to permit 115 a line word-space regulator to pass on; the escape pawl 350 adapted to release the next waiting line word-space regulator on the first upward movement of the bar.
147. In a machine of the class described an elevator for a circulating series of line word-space regulators, comprising the vibrating bar 383 pawls 382, in combination with the spring seated retaining latches 384. 120
148. In a machine of the class described, the combination with a plurality of line word-space regulators of a descending and an ascending runway therefor, a controller 125 having actuating line or galley pins, means called into action by said pins for transferring certain of the regulators from one runway to the other.
149. In a machine of the class described the starting or tripping device for a galley shaft substantially as described and shown, operated from a line pin in the controller, in combination the means substantially as described and shown, for delaying the action of the clutch to start said shaft. 130
150. In a machine of the class described the means substantially as described and shown for operating the word register, comprising arm 420, vibrating with every stroke of a key; pawl-carrying bell crank 417; latch 418; and the means for withdrawing the latch when the space bar is struck. 135
151. In a type-casting and composing machine, the combination with an alarm device, of a controller having actuating pins to select characters and spaces and special actuating pins set opposite the space representations to neutralize the action of the alarm device. 140
152. In a type-casting and composing machine the combination with a set-size index, of a reading finger or feeler bar adapted to be thrust yieldingly against the index, means for permitting the bar to make an excessive or abnormally long stroke when the index has not been moved, connections from the bar to limit or prevent the action of the pump when the feeler bar makes its long stroke. 145
153. In a type-casting and composing machine, the combination with means for casting type and shoulder-high spaces, of means for reducing the length of the spaces after they are cast. 95
154. In a type-casting and composing machine, the combination with means for casting type and shoulder-high spaces, and means for assembling said type and spaces into lines, of means for reducing the length of the spaces. 150
155. In a type-casting and composing machine, the combination with means for assembling type and shoulder-high spaces, of means for reducing the length of the spaces, for the purpose set forth. 155
156. In a type-casting and composing machine, the combination with means for casting type and shoulder-high spaces, and means for assembling the type and spaces into lines, of means for moving the spaces endwise relatively to the type, and means for cutting off the projecting portions of the spaces, for the purpose set forth. 160
157. In a type-casting and composing machine, the combination of means for casting shoulder-high spaces, with means for cutting off portions of said spaces, for the purpose set forth. 165
158. In a type-casting and composing machine, the combination with means for casting shoulder-high spaces, of means for reducing the length of said spaces, and means for assembling said spaces, together with appropriate type into lines. 170
159. In a type-casting and composing machine, the combination with a mold and means for casting type and shoulder-high spaces therein in order of composition, of means for reducing the length of said spaces after they are cast. 175
160. In a type-casting and composing machine, the combination with a mold and means for casting type and shoulder-high spaces therein in order of composition, of means for reducing the length of said spaces after they are cast, and means for assembling said type and shortened spaces into lines. 180
161. In a type-casting and composing machine, the combination with a matrix case, mold and casting mechanism, of means for indicating when a matrix character becomes stopped up. 185
162. In a type casting and composing machine, the combination with a matrix case, mold and casting mechanism, of an audible alarm for indicating when a matrix character becomes stopped up. 190
163. In a type-casting and composing machine, a device adapted to distinguish between perfect and imperfect type, and to sound an alarm for each imperfect type produced. 195
164. In a type-casting and composing machine, a plurality of matrices cooperating with the mold, a device for testing the type successively in the order in which they are cast, and means for sounding an alarm each time an imperfect type is tested. 200
165. In a type-casting and composing machine, the combination with a mold having a fixed alining slot, of a matrix case having parallel matrix bars, said bars having transverse wedge-shaped notches, and an impression plunger for seating a matrix bar in the alining slot, said plunger being wedge-shaped to cooperate with the notches on the matrix bar to give the bar its proper position on the mold. 205
166. In a typographic machine the combination with a matrix bar having ears at each end, of a mold, an impression device for seating the bar on the mold, and means for engaging said ears simultaneously to withdraw the matrix bar after it has been seated by said impression device. 210
167. In a type-casting and composing machine, the com- 215

- hination with a matrix bar having a plurality of matrices of a mold, means for seating said bar thereon and means for simultaneously and positively withdrawing both ends of said bar from the mold.
- 5 168. In a typographic machine, a matrix-placing mechanism comprising a series of slides, the adjacent slides being connected by a pin in one entering a slot in the other, said slots and pins being adapted to secure a uniformly stepped or graduated movement of one slide on another.
- 10 169. In a typographic machine, the combination with a matrix case, of a matrix-placing mechanism comprising a plurality of parallel slides, connected each to another so as to have uniformly limited movements on each other, means for placing the slides in uniformly stepped positions, and means for securing variable movements of the matrix case from the variable movement of said slides.
- 15 170. In a typographic machine, the combination with a matrix case, of a matrix-placing mechanism, comprising a plurality of adjacent parallel slides, connected each to another in a series so as to have a uniformly limited movement on each other, means for giving one of said slides a maximum movement; means for limiting another non-adjacent slide to a minimum movement, whereby the intermediate parts will occupy uniformly stepped positions, and means for securing a variable movement of the matrix case from said variably movable slides.
- 20 171. In a typographic machine, the combination with a matrix case, of a matrix-placing mechanism comprising a plurality of adjacent parts, connected each to another in a series so as to have a uniformly limited movement on each other, means for giving one of said parts a movement corresponding to the greatest movement of the matrix case, means for stopping the next adjacent part when it has moved one step less and so on to the last of the series, which has a movement corresponding to the minimum movement of the case, and means for securing a variable movement of the matrix case from the variably movable parts.
- 25 172. In a typographic machine, a matrix-placing mechanism comprising a plurality of adjacent parts, connected each to another in a series so as to have a uniformly limited movement on each other; means for giving one of said parts a maximum movement; means for limiting another non-adjacent part to a minimum movement, whereby the intermediate parts will be disposed in uniformly stepped positions.
- 30 173. In a typographic machine, the combination with a matrix case, of a matrix-placing mechanism comprising a plurality of adjacent parts, connected each to another in a series so as to have a uniformly limited movement on each other, means for giving one of said parts, a maximum movement, means for limiting another non-adjacent part to a minimum movement whereby the intermediate parts will be disposed in uniformly stepped positions and means for securing a variable movement of the matrix case from said movable parts.
- 35 174. In a typographic machine, the combination with a unit register adapted to record type units of a fixed size, of a justifier for effecting justification on the basis of units of another size.
- 40 175. In a typographic machine the combination with a
- unit register adapted to record type units of a fixed size, of a justifier for effecting justification on the basis of units of a larger size.
- 45 176. In a typographic machine the combination with a unit register adapted to record type units of a fixed size, of a justifier for effecting justification on the basis of units which are a multiple of the type unit.
- 50 177. In a typographic machine the combination with a registering device of a justifying device both devices being adapted to operate on the unit system—the unit of the registering device being smaller than the unit of the justifying device.
- 55 178. In a typographic machine the combination with a type unit registering device, of a justifying device, both devices being arranged to operate on the unit system—the unit of the registering device being a fractional part of the unit of the justifying device.
- 60 179. In a typographic machine, the combination with means for registering the amount of letter and normal word space in terms of an arbitrary unit, of means for effecting justification on the basis of an arbitrary unit of different size.
- 65 180. In a typographic machine, the combination with means for registering type space in terms of an arbitrary unit—of a justifier for effecting justification on the unit system—the unit of the justifier being a multiple of the type unit, and means for eliminating an odd type unit whereby the amount of space to be added to justify the line is a multiple of the justifying unit.
- 70 181. In a typographic machine, the combination with means for registering type space in terms of an arbitrary unit, of an independent device for varying one space in the line when the number of type units is an odd number.
- 75 182. In a typographic machine, the combination with means for registering type space in terms of an arbitrary unit, of a justifier adapted to operate on the basis of a unit which is a multiple of the type unit, independent means for reducing one space in the line when the number of type units registered is an odd number.
- 80 183. In a typographic machine, the combination with a justifier adapted to operate on the unit system, of means for registering type units in integral and fractional terms of the justifying unit.
- 85 184. In a typographic machine, the combination with a justifier adapted to operate on the unit system, of means for registering type units in integral and fractional terms of the justifying unit, and independent means for varying certain spaces of the line when the registering devices show a fractional remainder.
- 90 185. In a typographic machine, the combination with a justifier adapted to operate on the unit system, of a register adapted to record type units in terms of whole and half justifying units, and independent means for reducing one particular space in the line half a unit when the recorded type space is fractional.
- 95 186. In testimony whereof I affix my signature in presence of two witnesses.
- 100 WILLIAM E. BRAND.
- Witnesses:
- 105 WILLIAM N. SWAIN,
EDWARD N. CARPENTER.
